UNITED STATES PATENT OFFICE.

FRANK B. REDINGTON AND MICHAEL J. MILMOE, OF CHICAGO, ILLINOIS, ASSIGNEES,
BY MESNE ASSIGNMENTS, TO PACKAGE MACHINERY COMPANY, OF SPRINGFIELD,
MASSACHUSETTS, A CORPORATION OF MASSACHUSETTS.

WRAPPING-MACHINE.

1,117,442.

Specification of Letters Patent. Patented Nov. 17, 1914.

Application filed January 3, 1911. Serial No. 600,556.

To all whom it may concern:

Be it known that we, FRANK B. REDINGTON and MICHAEL J. MILMOE, citizens of the United States, residing at Chicago, in the county of Cook and State of Illinois, have invented certain new and useful Improvements in Wrapping-Machines, of which the following is a full, clear, and exact specification.

- 10 The invention relates to improvements in machines for wrapping small articles of merchandise and the like, such as sticks of chewing gum and various confections, and has for its object to provide an improved 15 machine of the character described which shall be rapid and accurate in its action, completely automatic, and capable of producing a securely wrapped package of an improved character.
- 20 To the attainment of these ends and to accomplish certain other new and useful objects which will appear, the invention consists in the features of novelty hereinafter described, shown in the accompanying drawings forming a part of this specification, and finally pointed out more specifically in the appended claims.

In the said drawings Figures 1 and 2 taken together form a complete top plan view of the machine with portions only of the power pulley, the fly wheel, the waxed paper reel and the delivery chute for the completed packages partly broken away. Fig. 3 is an end view in elevation of that portion of the machine above the top-plate, the view being taken on line 3—3, Fig. 1, looking in the direction indicated by the arrows. Fig. 4 is a view in sectional elevation on line 4—4 of Fig. 1, and Fig. 5 is a similar view on line 5—5 of Fig. 2, both views looking in the direction indicated by the arrows. Figs. 6 and 7 are sectional plan views taken just below the top-plate as indicated by lines 6—6 and 7—7 of Figs. 4 and 5 respectively, looking in the direction indicated by the arrows. Figs. 8 and 9 are sectional views in elevation on lines 8—8 and 9—9 of Figs. 1 and 2 respectively, looking in the direction indicated by the arrows, with parts broken away. Fig. 10 is a section on line 10—10, Fig. 2, looking in the direction indicated by the arrows through the binder-applying mechanism with parts broken away. Fig. 11 is a section through the gum magazine

and related mechanism on line 11—11, Fig. 55 1, Fig. 12 is a sectional view through the single stick transport and associated parts on line 12—12 of Fig. 1, looking in the direction of the arrows. Fig. 13 is a sectional view on line 13—13, Fig. 1, looking in the direction of the arrows, the view being designed to show among other details the multiple stick transport for delivering a plurality of single wrapped sticks to the multiple stick or tin-foil wrapping mechanism, with parts 60 broken away. Fig. 14 is a similar sectional view looking in the direction of the arrows on line 14—14, Fig. 2, through the multiple stick wrapping mechanism for applying the tin-foil, parts being broken away. Fig. 15 70 is a sectional view also through the multiple stick wrapping mechanism, showing the details of the multiple stick end folding mechanism and taken on line 15—15 of Fig. 2, looking as in the immediately preceding 75 views from the front to the rear of the machine. Fig. 16 is a sectional view taken through the machine on line 16—16, Fig. 2, disclosing for the greater part the details of construction of the transport for conveying the multiple stick package from the foil wrapping mechanism to the binder applying and wrapping mechanism, parts of the mechanism being broken away. Fig. 17 80 is a detail view of the entire waxed paper or single stick paper reel and feed mechanism including the associated paper shears or cutters and their operating mechanisms with parts of the frame and other adjacent parts broken away, the view being taken 85 on line 17—17 of Fig. 1. Fig. 18 is a detail in section of the single stick waxed paper reel and feed, being taken on line 18—18 of Fig. 3. Fig. 19 is a detail sectional view of the single stick waxed paper feed on line 90 19—19 of Fig. 18. Fig. 20 is a detail sectional view of the tension for the single stick waxed paper feed showing also details of the shears, the laterally moving gripper jaws for drawing the waxed paper longitudinally to the single stick folding mechanism and broken parts of the folding mechanism. Fig. 21 is a view of the same parts shown in Fig. 20 and illustrates the movement of the spring tension controlling the 100 waxed paper feed. Fig. 22 is an enlarged detail view in section of the gum magazine and the mechanism for positioning and feeding 105

the single sticks therefrom and is taken on the same sectional line as the view in Fig. 8. Fig. 23 is an enlarged detail plan view of the single stick gum positioning device 5 and feed, shown in Fig. 22 but with the magazine itself removed. Fig. 24 is a view similar to Fig. 23 showing the single stick gum feed and positioning device in their operated positions presenting the gum to 10 the gum picks for the first or the single stick wrapping operation. Fig. 25 is an enlarged detail sectional view through the single stick gum feed and positioning device being taken on line 25—25 of Fig. 24. Fig. 15 26 is a detail view of the laterally moving gripper jaws for drawing the waxed paper to the single stick wrapping mechanism, and their operating means. Fig. 27 is an enlarged detail view of the laterally moving 20 gripper jaws taken on line 27—27, Fig. 26. Fig. 28 is an enlarged sectional view taken on line 28—28 of Fig. 26, looking in the direction indicated by the arrows, but with the waxed paper feed gripper jaws in the 25 position indicated by dotted lines in said figure of the drawings in order to illustrate the manner in which the jaws are operated to open them to release the waxed paper. Figs. 29 and 30 are detail sectional views of 30 the gripper jaws taken on lines 29—29 and 30—30 of Figs. 27 and 28 respectively. Fig. 31 is an enlarged plan view of the single stick folding mechanism. Figs. 32 and 33 are sectional views on lines 32—32 and 35 33—33 respectively of Fig. 31. Fig. 34 is an enlarged detail side elevation of one of the first single stick end folders. Fig. 35 is an enlarged perspective view showing the detail construction of one of the second 40 single stick folders. Fig. 36 is a detail view of the multiple stick transport for transferring the singly-wrapped sticks of gum in multiple quantities from the single stick wrapping mechanism to the foil wrapping 45 mechanism, the view being taken approximately on broken line 36—36, Fig. 1. Fig. 37 is a sectional view taken through the top plate of the machine on line 37—37 of Fig. 1, showing the details of construction and 50 mode of operation of the single stick accumulator from which the single wrapped sticks of gum or other articles are taken in multiple quantities to the foil and binder applying mechanism. Fig. 38 is an enlarged detail view partly in section taken 55 approximately on line 38—38, Fig. 37. Fig. 39 is an enlarged detail view of the single stick transport and the mechanism for operating, the view being taken on line 39—39 60 of Fig. 13; and Fig. 40 is a view in section illustrating the details of construction of the same, being taken on line 40—40 of Fig. 39 looking in the direction indicated by the 65 arrows. Fig. 41 is an enlarged detail view in section corresponding with the view

shown in Fig. 8, illustrating the position of the parts of the single stick transporting and folding mechanism, the position of various parts being at the instant a single stick of gum is delivered from the gum magazine to the single stick gum picks. Fig. 42 is a view similar to Fig. 41 but showing the relative position of the same parts at the instant that the single stick of gum is delivered by the gum picks on top of a 70 waxed wrapper over the single stick folding mechanism. Fig. 43 is a broken view similar to the two preceding figures showing the position of the various parts at the instant that the single stick with its wrapper 75 has been forced by the gum picks to the bottom of the folding box, the longitudinal sides of the wrapper being folded to the vertical position. Fig. 44 is a view similar to the views immediately preceding, showing the next step in the operation of folding a single stick, the tucker for folding the rear side flap having advanced and folded the same down flat upon the stick or package. Fig. 45 is a view similar to Fig. 44 80 and the immediately preceding views showing the next succeeding step in the operation of wrapping a single stick, the picks being withdrawn and the partially wrapped single stick shown in the process of being 85 discharged from the folding box under the spring pressed plate at the forward side of the box which folds the remaining side flap of the single stick wrapper, the stick being 90 grasped by the reciprocating single stick feed mechanism and it is during its passage under this spring pressed plate that the ends of the wrapper are folded upon the stick by the folding means already referred to in Figs. 31 to 35 inclusive. Figs. 46, 47 and 48 represent the single stick in three successive stages of the folding operation: Fig. 46 showing the stick with the last side flap folded by passing under the edge of the spring pressed plate, as illustrated in Fig. 45; Fig. 47 representing an intermediate stage of the folding of the end flaps by the end folders shown in detail in Figs. 31 and 32, while Fig. 48 represents the completed single stick package with the end flaps folded flat against the underside of the package as the package emerges from under the spring pressed plate, which last step in the 100 operation of folding is accomplished by the folding mechanism shown in detail in Fig. 31 and particularly in the sectional view, Fig. 33 and detail view Fig. 35. Fig. 49 is a view similar to Fig. 45 and the immediately preceding views but shows the single stick transport and folding mechanism in 105 position to deliver from the multiple stick accumulating chamber a plurality of completely folded single sticks or packages of the form shown in Fig. 48 to the multiple stick transport for delivery to the tin foil 110 125 130

wrapping mechanism. Fig. 50 is an enlarged detail sectional view of the multiple stick transport which conveys the completely folded single sticks in multiple groups to the tin foil wrapping mechanism. In this view an enlarged sectional detail of the tin foil wrapping mechanism is also shown. The entire view in this figure is taken on the same vertical section as Figs. 8 and 9, parts being broken away and the parts shown enlarged. Fig. 51 is a view similar to Fig. 50 showing the multiple stick transport in the position where the multiple sticks for forming the completed package are being delivered to the tin foil or multiple stick wrapping mechanism. Fig. 52 is a sectional view showing a detail of the multiple stick tin foil wrapping mechanism, the multiple stick package being pressed into the folding box causing the longitudinal side flaps to assume the vertical position shown preparatory to the folding of the first side flap, which operation is illustrated in the similar view in Fig. 53. Fig. 54 is an enlarged horizontal sectional view of the first side flap folder, the operation of which is shown in Fig. 53, the view being designed to show in detail the means for indenting or creasing the lateral edges of the first folded side flap of the wrapped multiple stick packages which causes the same to assume the form illustrated in enlarged detail in Fig. 55. Fig. 56 is a detail view illustrating the relative positions of the folding mechanism in the operation of folding the completed package succeeding that illustrated in Figs. 53 to 55 inclusive, the package having been passed under the spring pressed plate and the last longitudinal side flap folded flat upon the package. In this view the package is shown in position so that at its next advance movement the two remaining lateral edges adjacent the ends of the package will be crimped or folded inwardly by the folding means which is shown in the enlarged sectional view in Fig. 57 and the package is caused to assume the form shown in the perspective view in Fig. 58. Fig. 59 is an enlarged detail sectional view illustrating the next succeeding step in the operation of folding the wrapper around the multiple stick package. In this view the end folder which in the immediately preceding views was referred to as carrying the end crimping means is shown depressed folding the ends of the multiple stick wrapper at approximately right angles to the length of the stick. Fig. 60 is a detail sectional view similar to Fig. 59 illustrating the next succeeding step in the operation of folding the wrapper around the multiple stick package, the end folders being shown advanced folding the end flaps up flat against the under side of the package. Fig. 61 is a perspective view of a completely wrapped multiple stick pack-

age before the binder is applied, the same being the form the package assumes before delivery to the package transport and the form the package assumes after the operation of folding down the end flaps illustrated in Fig. 60. In this view, however, the package is inverted in order to show more clearly the details of the end folds of the package. Fig. 62 is an enlarged sectional view through the top plate of the machine taken on line 62-62 of Fig. 2, the view corresponding to the enlarged detail view heretofore referred to in Fig. 60, but in this latter view the mechanism for operating the end folders is shown in detail, other adjacent parts of the machine being broken away. Fig. 63 is an enlarged plan view of the multiple stick folding mechanism, the member carrying the multiple stick end folding means being shown in section. In this view a portion only of the multiple stick transport for conveying the wrapped multiple stick package to the binder applying mechanism is shown, the remainder being broken away. Fig. 64 is a detail view partly in section showing the construction and mode of operation of the feed mechanism which causes the multiple stick package to be moved through the multiple stick folding mechanism, as shown more clearly in enlarged plan view, Fig. 63, being on line 64-64 of Fig. 7. Fig. 65 is an enlarged detail view of a multiple stick package transport which carries the wrapped multiple stick package from its wrapping mechanism to the binder applying mechanism traveling approximately through an arc of 180°. In this view parts of the top plate are shown in section. Fig. 66 is a sectional view through the multiple stick transport shown in detail in Fig. 65; this view, however, being taken on line 66-66 of Fig. 2, looking in the direction indicated by the arrows. Fig. 67 is a detail sectional view through the top plate of the machine on lines 67-67, Fig. 2, and shows the cam and its associated mechanism for operating the multiple stick transport of Fig. 65. Fig. 68 is a detail sectional plan view taken on broken line 68-68, Fig. 66, and also on line 68-68 of Fig. 67. In this view a fragment of the means for operating the jaws of this multiple stick transport to cause it to open to receive the wrapped package is shown. Fig. 69 is a fragmentary view of the mechanism for applying the binder around the wrapped multiple stick package. This view is similar to Fig. 5 which is an assembled view showing the relation of the same parts to the other parts of the mechanism. This view differs from the similar view of the same parts in Fig. 5 in that it shows the clutch mechanism under the control of the multiple stick package while in the binder applying mechanism operated to throw the binder applying mechanism into gear or op-

- erative relation with its actuating means. Fig. 70 is an enlarged sectional view taken on line 70—70 of Fig. 69 showing the details of construction of the clutch controlling the binder applying mechanism, and Fig. 71 is a fragmentary view of the clutch controlled cam which drives the binder applying mechanism and the view shows also a portion of the lever which, coöperating with the peripheral surface of the cam, operates to disengage the clutch in order to stop the operation of the cam when for any reason the machine has failed to deliver the package to the binder applying mechanism. Fig. 72 is an enlarged sectional plan view taken on the line 72—72 of Fig. 5, and showing the details of construction of the binder feed and binder wrapping and discharging mechanisms. Fig. 73 is an enlarged detail view of the mechanism for driving the cut binder feed which delivers the cut binders from the binder magazine to the binder applying and pasting mechanism. The view also shows a detail of the folder for folding the first side flap of the binder and the mechanism for discharging the package from the binder folding box. Fig. 74 is a detail view greatly enlarged of the wrapped package transport which conveys the wrapped package to the binder applying mechanism, the view showing the pivoted transport in the position where a wrapped package has just been delivered to the binder applying and folding mechanism. In this view the parts which grasp and hold the wrapped multiple stick package during the part of the process of applying the binder is shown in detail including parts of the mechanism for automatically throwing the binder feeding and applying mechanisms into gear by reason of the introduction of the wrapped multiple stick package into the binder applying mechanism. In this view all parts are about twice the relative size of the same parts shown in Fig. 2. Fig. 75 is a detail sectional view showing the construction and the manner in which the vertical shaft which carries a portion of the binder wrapping mechanism is operated. The view is taken approximately on broken line 75—75 shown in Figs. 7 and 74. Fig. 76 is an enlarged detail sectional view taken on the same section line as Fig. 10 showing details of the binder feed mechanism and the binder applying, folding and pasting mechanisms. In this view the wrapped package is shown as just being brought into contact with the binder which has been brought to position over the top of the binder folding box and under the paste applying roll. Figs. 77, 78 and 79 are broken detail sectional views similar to Fig. 76 and illustrating the successive steps in the application of the binder to the wrapped multiple stick package; Fig. 77 showing the relative positions of the parts adjacent the binder folding box when the wrapped package has been forced by the pivoted transport into the binder folding box and has caused the longitudinal edges of the binder to be folded to the vertical position thus covering three sides of the package and at the same time operating the clutch, which throws the binder applying and ejecting mechanism into gear; Fig. 78 showing the succeeding step in the operation of applying and pasting the binder in which the package, having been forced to the bottom of the folding box, the rear side folder has moved forwardly folding the rear side flap flat upon the package; and Fig. 79 showing the next and last step in the operation of applying the binder to the wrapped multiple stick package in which view the package is shown as being ejected from the binder folding and applying mechanism, the last or forward side flap being folded and pasted down flat upon the package being forced by the package ejecting mechanism under the spring pressed roller and ledge at the forward side of the binder folding box. Fig. 80 is a sectional view through the entire binder applying and pasting mechanism and through the completely wrapped package discharge mechanism, being taken on the same section lines as the immediately preceding figures. This view also discloses the details of the improved wrapped package discharge device by which the completely wrapped packages may be readily and conveniently discharged in desired quantities in suitable boxes or cartons, such a box or carton being shown at the discharge end of the device in this figure and further illustrated in the plan view, Fig. 81, showing substantially the same parts. Fig. 82 is a perspective view of a completely wrapped multiple stick package having the binder applied thereto as it comes from the machine; Fig. 83 is an enlarged sectional view showing the details of construction by which flexibility is secured in the upper roller for feeding the cut binders to the binder applying mechanism, the view being taken approximately on broken line 83—83, Fig. 76, and Fig. 84 is an enlarged sectional view showing the inner details of construction of one of the gripper jaws which seize and hold the multiple-stick package during the operation of applying and pasting the cut binder around the multiple-stick package after the application of the foil wrapper.
- Before referring to the specific details of construction of our improved wrapping machine, as shown in the present embodiment, it is thought desirable first to describe in detail the style of package which the mechanism is designed to produce. For this purpose reference is first made to Figs. 41 to 48 inclusive, illustrating the single stick package and the operations incident to the

formation of the same. Although, as stated, the machine may be employed for wrapping various articles of merchandise, the particular embodiment of the invention shown is 5 adapted to the wrapping of chewing gum, and the single stick of gum,—hereafter called the "single stick",—is indicated by the reference character 10. In the present embodiment of the invention each single 10 stick is individually wrapped with a waxed or paraffin wrapper 11 in the manner illustrated in Figs. 42 to 47 inclusive, the completely wrapped single stick being shown in Fig. 48, from which it will be seen that the 15 longitudinal side flaps of the wrapper 11 are first folded down flat upon the package and then the projecting end portions are folded over and down flat upon the package. A plurality of these wrapped single sticks, as 20 shown complete in Fig. 48, usually in groups of five, are accumulated as shown in Fig. 50, and a foil wrapper of sufficient size to envelop the entire package is applied as illustrated in Figs. 51 to 56 inclusive, Fig. 58 25 representing the enveloped multiple stick package around which the foil wrapper 12 has been applied and the package prepared for the end folding process illustrated in Figs. 59 and 60, the completely foil-wrapped 30 multiple stick package being shown in Fig. 61. In Fig. 74 the multiple stick foil-wrapped package 12 is shown transferred to a position where a binder is to be applied and in Fig. 76 said binder, indicated by the 35 reference character 13, is shown in position ready to be wrapped and pasted around the foil-wrapped multiple stick package. Figs. 77 to 79 inclusive, show the succeeding steps resulting in the completed multiple stick 40 foil-wrapped package with binder applied, as shown also in the enlarged detail view, Fig. 82. In the formation of this improved multiple stick foil-and-binder-wrapped package, among the more important features 45 are the method and the mechanism for creasing inwardly, as at 12^a, the side edges of the foil wrapper adjacent the ends thereof before the end folding operation, as shown in Figs. 55 and 58 illustrating the article, and 50 in Figs. 54, 56 and 57 illustrating the means for accomplishing this purpose and its mode of operation. This creasing inwardly of the foil wrapper adjacent the ends is of the highest importance in enabling the foil 55 wrapper 12 to be closed at its ends in an effective manner to prevent the material within the package from being affected by the atmosphere, and also makes a fold having a neater appearance, thus giving the package 60 a more sightly appearance at the ends after the binder is applied.

In the application of the paraffin wrappers around the single sticks and the foil wrapper around the multiple stick package 65 no adhesive material need be applied, be-

cause these parts are retained in position securely and effectively covering the package and each single stick therein by the binder, which is secured in position around the completed multiple-stick package by a suitable 70 adhesive in the manner and by the means hereinafter described; but the binder itself, unlike the single stick paraffin wrappers 11 and the multiple stick foil-wrapper 12, extends in width preferably only the length of 75 the foil wrapped multiple stick package or a little less, thus binding the folded ends of the wrapped multiple stick package securely in position without any parts projecting beyond the ends to be folded. 80

The various operations in forming the completed package, as described, consists in first delivering the single stick from the magazine (Fig. 41) to a point immediately above the single stick folding mechanism: 85 then drawing from the paraffin wrapper reel by a suitable paper feed mechanism the single stick wrapper, (Figs. 20 and 21); severing the single stick wrappers from the rolls or strips from which they are drawn; depositing the paraffin wrapper in proper position under the stick and over the folding mechanism, (Fig. 42); depressing the stick into the wrapping mechanism and folding the longitudinal side flaps to the vertical position (Fig. 43); folding down the rear side flap (Fig. 44); folding the forward side flap by passing the stick out of the single stick folding box under the spring-pressed plate, (Fig. 45), during the continuation of which 90 movement the ends of the wrapped single sticks are folded flat upon the sides of the single stick package (Figs. 32 and 33) whence the wrapped single sticks are delivered to the multiple stick accumulating 95 chamber, (Fig. 45); delivering the wrapped single sticks in multiple quantities to the foil wrapping mechanism over the cut foil-wrapper (Figs. 50 and 51); depressing the multiple stick package into the foil wrapping mechanism and folding the longitudinal side flaps to the vertical position (Fig. 52); completing the side and end folding operations on the foil wrapper (Figs. 53 to 100 60 inclusive); delivering the foil-wrapped multiple stick package to the binder applying mechanism immediately over the previously positioned cut and gummed binder (Figs. 65, 74 and 76); depressing the package into the binder wrapping mechanism 105 and folding the longitudinal side flaps to the vertical position (Fig. 77); folding the rear flap of the binder, (Fig. 78); discharging the package from the binder wrapping box and at the same time folding and pasting the forward binder flap, (Fig. 79); and finally 110 discharging the completely wrapped packages from the machine and depositing the same in suitable packing boxes or receptacles (Figs. 80 and 81). 115 120 125 130

In the construction and organization of a package wrapping machine embodying the herein described invention and improvements, it will be apparent that any suitable frame or supporting structure may be used on which to mount and support the various mechanisms but the preferred construction is that herein described and shown and comprises a suitable top-plate or table indicated by the reference character 30, the outline of which is shown most clearly in the plan view of the machine in the companion drawings, Figs. 1 and 2. (See also sectional views of the same in the companion drawings Figs. 4 and 5, and other sectional views throughout the drawings, and the front view in elevation, Fig. 3.) The table 30 is preferably of a general rectangular form, as shown, and is provided with various openings and recesses to receive moving parts, as shown and hereinafter explained. Aside from the table 30, the main frame of the machine comprises a suitable under structure upon which the table is mounted, as indicated at 31. This under supporting structure for the table may be cast integrally with the table top, as shown, or it may be formed separately from the table and secured thereto in any well known manner. For the most part, the under supporting structure 31 comprises downwardly extending legs at the corners of the table and suitable cross connecting members and various shapes of these parts for the purpose of receiving the various mechanisms and supporting the same as described.

The main drive shaft is indicated by the reference character 50 (Figs. 1 and 6) and extends horizontally across the front of the machine and is journaled in suitable bearings 51, 52, in the under structure 31 in the bottom of the machine. This shaft is driven by a suitable pulley 53 which receives a belt from any desired source of power. The pulley 53 is loose on shaft 50 but is provided with some suitable clutching means by which it may engage and rotate shaft 50, as, for example, the toothed portion of its hub, as shown in dotted lines, Fig. 1, at 54, which engages a similar toothed portion on clutch 55 mounted to rotate with, but slideable on, shaft 50 and is provided with a grooved portion as indicated at 56, adapted to receive a fork, the branches of which are indicated at 57, 58, and which fork is secured to the rocker rod 59 extending along the left-hand side of the machine from front to rear and being pivoted at its extremities at 60 and 61, thus putting the driving clutch under the immediate control of the operator whether the operator happens to be at the front of the machine near where the completely-wrapped packages are delivered or whether at the rear of the machine near the binder pasting

and wrapping mechanism. Such control is obtained through suitable operating levers 62 and 63 on rock shaft 59. Secured to the outer extremity of drive shaft 50 beyond pulley 53 is a fly-wheel 54^a with an outer hand rim which the operator may grasp to move the drive shaft slowly when the clutch is operated to allow the drive pulley to rotate freely on the drive shaft. Drive shaft 50 has mounted on it, intermediate its ends and between bearings 51 and 52, bevel gears 64, 65, which will be presently further described. The thrust from these bevel gears is taken by collar 66 adjacent bearing 51. The main drive shaft 50 also carries cams 67, 68 and 69, for a purpose to be later described. Mounted in suitable bearings in the under structure 31 and extending longitudinally of the machine and parallel with main drive shaft 50, are other drive shafts 70, 71, 72, 73 and 74; shaft 70 being supported at its extremities by bearings 75, 76, and held against end thrust by collar 77; shaft 71 by bearings 78, 79 and held against end thrust by collar 80 adjacent bearing 78; shaft 72 by bearings 81, 82 and collar 83 to take end thrusts; shaft 73 by bearings 84, 85 and collar 86; and shaft 74 is supported by bearings 87 and 88 shown only in Fig. 16, these bearings being hidden from view in Fig. 7.

The main drive shaft 50 is provided near the end remote from the driving pulley with two gears 89 and 90, the first being keyed to this shaft just on the inside of the under structure 31 and meshing with the idler gear 91 which in turn meshes with gear 92 and driving the shaft 70. The gear 90 is keyed to shaft 50 on the exterior of frame 31 and is in mesh with idler gear 93 which in turn meshes with a large gear 94 keyed to the end of and driving the shaft 71. The shaft 71 on the inside of frame 31 has keyed to it gear 95 which meshes with idler gear 96 secured on the main frame at 97. Gear 96 is in mesh with gear 98 on shaft 72 which in turn meshes with gear 99 on shaft 73 (Figs. 14 and 15), and gear 99 is in mesh with gear 100 above shaft 74, which is the last of the longitudinal shafts and the one farthest remote from the main drive shaft 50. The gear 100 has its bearing indicated at 101 and this gear is in mesh with another similar gear 100^a just below it on the end of shaft 74 (see Fig. 16) and by these means rotation is imparted to this shaft. The gear on the shaft 74 is immediately below the gear 100 (shown in Fig. 7) and is not illustrated in the drawings, since in form it corresponds with gear 100.

In addition to the longitudinal shafts 50, 70, 71, 72, 73, and 74 and their actuating means as described, in the under structure of the machine four counter-shafts are pro-

vided for purposes which will be presently described. On the right hand side of the machine there are two of these counter shafts, as indicated by the reference characters 102, 103, (Figs. 4 to 9 inclusive). These counter-shafts are for the purpose of driving the mechanism for operating the paper feed mechanism and the tin foil feed mechanism. The counter shaft 102 lies in the plane of drive shaft 50 and is supported by brackets 104 and 105 and in which suitable bearings are provided and is driven by bevel gear 106, meshing with bevel gear 65 on shaft 50. At the end opposite the bevel gear drive this shaft is provided with sprocket wheel 107 for driving a link belt. Counter shaft 103 is similar in construction to counter shaft 102 and lies in the plane of longitudinal shaft 71, is supported on brackets 108, 109, provided with suitable bearings. This counter shaft is driven from shaft 71 by bevel gear 110 carried thereby meshing with a similar gear 111 on the end of the shaft. At the opposite end this counter shaft is provided with link belt sprocket wheel 112. At the opposite side of the under structure of the machine and lying also in the horizontal planes of shafts 50 and 71 and extending at right angles there-to are counter shafts 113, 114, shaft 113 being driven by bevel gear 64 on drive shaft 50, which meshes with similar bevel gear 115 on the abutting end of this shaft. Shaft 114 likewise is driven from bevel gear 116 keyed to shaft 71 which meshes with similar gear 117 on its abutting end. Shafts 114, 113, are mounted to rotate in suitable bearings on under structure 31, as indicated at 118, 119 and 120, respectively. By referring to the companion plan views (Figs. 6 and 7) of the under structure of the machine, it will be seen that the longitudinal shafts and the counter shafts which have just been described are provided with numerous cams and other instrumentalities for operating various portions of the folding mechanism, all of which will be presently referred to and described in detail.

The construction and mode of operation of the various mechanisms for the production of the completely wrapped multiple stick package will now be described following the order of the progress of the single sticks of gum from the time they enter the machine until the completely wrapped multiple stick package is discharged therefrom. The single sticks of gum indicated by the reference character 10 are fed in quantities to the gum magazine near the front side of the machine, which is composed of vertical channeled-standards 121, 122, (Figs. 1, 3, 4, 8, 11, 22 and 41). These vertical channeled-standards are spaced a suitable distance apart and may extend upwardly any desired height to receive and

hold any quantity of articles or sticks of gum 10 that are superimposed one above another in a vertical stack or column. The opposing channeled-faces of the standards 121, 122, guide the ends of the articles and retain them in a column or stack for discharge in a downward direction from the magazine. At their lower open ends the standards 121, 122 may be supported by suitable brackets 123, 124, to which they may be secured by screws 125, 126, as shown. The brackets 123, 124 may be secured to the table 30 in any desired manner, as by the bolts 127. The channeled-standards 121, 122 being in a vertical position, the quantities of sticks of gum contained therein will be fed downwardly by gravity and the bottom of the magazine being open, it is designed that the single sticks of gum shall be fed one at a time from the bottom of the magazine to the adjacent single stick wrapping mechanism. To provide an efficient and reliable feeding mechanism, the table 30 is provided with an opening in front of the gum magazine, as indicated at 32 (Figs. 22 to 24, inclusive), this opening extending longitudinally from the front of the machine toward the bottom of the magazine. Along the sides of this opening 32, which comprises approximately parallel ways or guides, a block 128 is mounted to reciprocate and said block carries on the upper side thereof two forwardly extending parallel arms 129, 130, which are adapted to lie underneath the lower open extremity of the gum magazine. These members 129, 130 are provided with depressions adapted to register with the bottom of the gum magazine in a well known manner, such depressions being indicated by the reference character 131, and being of sufficient depths to receive one, and only one, stick of gum at a time. Suitable means is provided for moving the reciprocating block 128 and comprises plate 132 secured to the bottom of block 128 by machine screws 133 and having a depending projection 134 to which is pivoted at 135 link 136 having pivotal connection at 137 with rocker arm 138, which extends downwardly into the under structure of the machine and is pivotally mounted at 139 on a bracket of frame 31. The lower extremity of rocker arm 138 is in contact with a suitable groove 68^b in cam 68 on driving shaft 50. (See Fig. 8.) By this construction the rotation of main drive shaft 50 imparts the desired reciprocating motion to the parallel feed arms 129, 130, causing them on each reciprocation when the gum magazine is full to remove a single stick of gum, and only one, from the under side of the stack or column within the magazine and to convey the same to a point where the single stick of gum will be engaged by the gum picks for feeding the same into the single

stick folding mechanism which will presently be described (see Figs. 22 to 24 inclusive, and Fig. 41).

In order to insure that the gum feed mechanism shall not fail to engage a single stick of gum, at each reciprocation thereof, we employ improved means for loosening the bottom sticks from the stack and causing the rear side of the lowermost sticks in the stack to drop with certainty into the feed depressions 131. This is an important feature of the invention when the character of these individual sticks of gum is considered. It is well known that the materials of which chewing gum and other confections are made are ordinarily of a character that causes the individual sticks to readily adhere to each other, particularly under certain conditions of atmosphere. To avoid difficulty in the handling of individual sticks of gum, it is common to use powdered sugar to freely coat the individual sticks but even when this is done, it is still found highly desirable to provide every means possible to insure precision and regularity in the feed. The preferred means for accomplishing this certainty of feed of the sticks at the lower part of the magazine comprises one or more members 140 pivoted at 141, preferably to the lower extremity of the grooved magazine standards 121, 122. These members 140 are provided with eccentric portions which are adapted to lie without the vertical plane of the interior portion of the magazine when held in their normal nearly vertical position by means of springs 142 secured to their upper extremities at one end and at the other end to the grooved standards of the magazine. These pivoted feed members 140 are provided with considerably elongated depending portions 143 which are adapted to be engaged by pins 144 on the reciprocating single stick feed members 129, 130.

Precision and regularity in the feed of the gum sticks under certain conditions is also found to be greatly improved by giving the parallel feed arms 129 and 130 a short secondary vibration or oscillation while the slots in the feed arms are immediately beneath the discharge end of the gum magazine. This is accomplished by a short irregularity as indicated at 68° in groove 68^b of cam 68. The secondary vibration of the feed arms so secured is found to assist in loosening the bottom gum stick and assist materially in causing it to settle to the bottom of feed slots in arm 129, 130. This improvement may be used in conjunction with the pivoted eccentric members 140 or without them, as desired.

In connection with the single stick feed mechanism we provide another improvement which is designed to insure the correct longitudinal position of the single sticks of gum as they are delivered by the feed mecha-

nism to the gum picks. This is an important feature of the invention because the gum picks themselves have a fixed movement in a vertical plane over the single stick folding mechanism and should the single sticks of gum for any reason be presented to the gum picks out of normal position they would be presented to the folding mechanism in the same relative position and consequently might not register properly with the folding mechanism which would result in breaking the stick in thus attempting to improperly introduce it into the folding mechanism and would probably result in clogging the machine. This mechanism comprises two arms 145, 146, lying above and approximately parallel to the parallel reciprocating feed members 129, 130, and being pivotally mounted on the tops of members 129 and 130, being connected to members 129, 130, at 147, 148 and pivotally connected to each other at 149. The pivotal connecting pin 149 extends downwardly (see Fig. 22) and at its lower extremity it has attached to it the forward end of spring 150 which is secured at its other end to fixed pin 151 on reciprocating block 128. Pivoted arms 145, 146 are suitably formed at their forward extremities as indicated at 152, 153, to enable them to grasp the individual sticks of gum 10, (Figs. 22 to 25 inclusive).

The details of construction of the gum magazine and feed having been treated, its operation will now be described. There being a stack of individual sticks of gum in the gum magazine, (as illustrated, for example, in Figs. 8 and 41), and the machine having been put in motion, the longitudinally movable block 128 will be reciprocated by the rotation of main drive shaft 50, cam 68, pivoted arm 138 and link 136 and caused to assume the position of the parts indicated in Fig. 22. This will bring the parallel reciprocating feed arms 129, 130, to a position where the individual stick gum slots 131 in their forward extremities, as described, will register with the lower open end of the gum magazine comprising the upright members 121, 122, already described. The column of gum will then descend in the gum magazine partly by gravity and if there is any tendency for the column to stick in the magazine, the eccentric feed members having been actuated to the position shown in Fig. 22 by which the pins 144 engaging the lower extremities 143 of the same will actuate their eccentric portions against the tension of springs 142 to the position of the parts indicated in Fig. 22 and this action will crowd the lower sticks of gum in the column with in the receptacle downwardly and cause the bottom stick to register completely within feed slots 131. It will be observed that the individual stick pivoted end guides 145, 146, are at this time actuated to the position illus-

trated in Fig. 23 so that their forward clamping ends 152, 153, are separated so that they do not come in contact with the gum while under the magazine. The actuation of 5 the pivoted guides 145, 146, to separate them against the action of spring 150 is accomplished as follows: One of these pivoted arms, as, for example, arm 146, is shown as provided with an extension 146^a extending 10 toward the front of the machine and beyond the pivotal connection 148. Bearing against this extension is roller 154 on the end of arm 155, which is secured to the upper extremity of rock shaft 156. (See Figs. 1, 23 and 24). 15 Rock shaft 156 extends vertically downward through a suitable bearing in bed plate 30, (Fig. 4) and is normally actuated by tension spring 157 secured at one end to pin or arm 158 on this shaft and at its other extremity 20 to a suitable fastening on bed plate 30, as, for example, pin 159. At the lower extremity of rock shaft 156 is a crank arm 160 provided with a pin or preferably an anti-friction roller, as shown at 161, adapted to engage 25 the cam face 68^a of cam wheel 68 on main drive shaft 50. A single stick of gum having entered the feed slots 131 in reciprocating arms 129, 130, the reciprocating block 128 is then caused to move toward the rear 30 of the machine by its actuating connections with drive shaft 50 already described, which movement will carry a single stick of gum to a position relative to the magazine, as indicated in Figs. 24 and 41. This movement of 35 the single stick feed mechanism by causing the parallel reciprocating arms 129, 130 to be carried rearwardly of the machine will obviously carry pins 144 in the same direction and release the eccentric feed members 40 140, which, under the action of springs 142, will cause the eccentric portions to lie wholly without the vertical forward plane of the interior of the magazine so that they will not engage the column, such being the relative 45 position of the parts, as shown in Fig. 8. By noting the position of the single stick feed comprising the parallel arms 129, 130, as they pass under the gum magazine, as shown in Figs. 8 and 41, it will be seen that 50 their portions rearwardly of the feed slots 131 are elevated so that they contact closely with the open bottom of the gum magazine and prevent the escape or disarrangement of any of the individual sticks in the column 55 until the parts have been returned to a position to feed the next succeeding bottom stick from the column. The plan view in Fig. 24 also indicates the relative position of these parts when the individual sticks have been 60 fed forwardly to a position immediately over the single stick folding box.

From an inspection of the single stick feed mechanism as shown in Figs. 23 and 24, it will be seen that at the instant the stick is taken from the under side of the

column in the gum magazine, the end positioning device is inoperative as described and as shown in Fig. 23. At the instant, however, that the single stick feed has carried the stick its own width from under the 70 gum magazine, the vertical rock shaft 156 is actuated at its lower extremity by cam track 68^a which causes arm 155 and roller 154 to move to the position shown in Fig. 24, thus allowing arms 145, 146 under the 75 tension of spring 150 to be brought to a position where they will engage the ends of the stick, which movement of these arms will properly adjust the stick longitudinally in the slots in the reciprocating parallel 80 feed members and which properly position the stick relative to the single stick folding mechanism. When the single sticks of gum 10 are thus brought to the position immediately over the single stick folding mechanism (as shown, for example, in Fig. 41), they are next engaged by the gum picks, of which there are two, as indicated by the reference characters 162, 163, (see Figs. 41 to 45 inclusive and others). At the same 85 instant the picks engage the gum stick, the cam track on cam 68 releases rock shaft 156 and permits the rocker arm 155 on the upper extremity thereof to engage the extension 146^a on arm 146, thereby operating both 90 arms 145, 146, on their pivotal supports and causing their portions 152, 153 to spread, as indicated in Fig. 23, such movement being against the tension of spring 150, thus releasing the stick. The lower 95 extremities of the gum picks 162, 163, are provided with a plurality of points 164, which pierce the sticks of gum near each end of the sticks. The movement of the gum picks is such that the sticks are fed forwardly 100 over the folding box, the picks are first depressed and impale the gum sticks after which they are given a slight upward movement, lifting the sticks out of the gum slots 131 of the feeding device which then withdraws and the gum picks are then depressed bringing the stick 10 immediately in position over the folding mechanism as illustrated in Fig. 42. The gum picks 162, 163, are secured to the cross head 165 (Figs. 1, 105 4, 8, 11 and 12). This cross head 165 is adjustably secured on the vertically reciprocating shaft 166 to which it is adjustably secured by set screw 167. The vertically reciprocating member 166 is carried in a suitable bearing 168 secured to the top plate 30 (see Fig. 12) and is provided at its lower extremity with a roller 169 in engagement with cam track 170 in cam 171 which is keyed, as illustrated, to shaft 70 (see 110 Fig. 4).

The mechanism for supplying the paraffin wrappers to the single stick folding mechanism will now be described: (see particularly Figs. 1, 3, 11, 17 to 21 inclusive, 115

and Figs. 26 to 30 inclusive). Near the forward right-hand corner of the top plate is the paraffin paper roll which is rotatably mounted on the pin 172 secured at the top of support 173 which is mounted on top plate 30. The paraffin paper roll comprises a hub portion 174 adapted to be journaled on pin 172 and held in position thereon by retaining member 175 provided with pin 176, which passes through a suitable hole in the end of pin 172. This retaining member is preferably no larger in diameter than the outer reduced end of hub 174, thus permitting the removable flange 177 of the roll to pass to its adjusted position over the reduced outer end of the hub where this flange is locked in position by one or more pins 178, in the reduced outer end of hub 174, these pins being adapted to engage with suitable cam surfaces 177* on the hub of the removable flange. The hub 174 and its inner extremity has a slightly reduced portion adapted to take circular flange 179 which is permanently secured to the hub by rivets, as shown, or other suitable means. By this construction we provide an improved paper roll in which the supporting flanges are readily separable, the outer flange 177 being provided with suitable grooves in its hub portion adapted to register with pins 178, which construction is exceedingly convenient in placing the paper rolls in position on the machine. As the paper is drawn from the roll by the paper feed mechanism, to be presently described, it is found that the momentum imparted to the roll particularly when the supply of paper thereon is greatest may have a tendency to cause the roll to continue to rotate even after the paper feed mechanism has ceased to operate, thus causing the paper to depend from the roll in a loop which may cause the strip to be torn, and is for many reasons objectionable. To prevent this over-running of the roll, we provide suitable adjustable brake mechanism for the roll comprising the flexible arm 180 secured at one extremity to the upright 173, and carrying at its other extremity a suitable braking member 181 in engagement with the circular flange 179 of the roll. This brake is adjustably controlled by thumb screw 182 which is adjustably mounted on upright 173 and at its outer extremity engages flexible arm 180.

The paraffin paper is directly fed from the above described roll by being passed between the feed rolls 183, 184, which are carried on support 173 which is below the paper roll. Roll 183 is carried by a fixed bearing on support 173 and is adapted to be positively driven by sprocket 185 and sprocket chain 186, which extends downwardly and engages sprocket wheel 107 heretofore described (see Fig. 6). On one end of the

positively driven roll 183 is gear 187 adapted to normally mesh with and drive gear 188 on feed roll 184. Roll 184 is journaled on a suitable frame 189 pivoted on upright 173 at 190 and normally held under spring pressure in the direction of fixed roll 183 by coil spring 191, one end of which engages frame 189 and the other upright 173. The upper free end of the frame 189 may be provided with hand projection 192 by which the frame may be caused to operate on pivot 189 to separate the roll 184 from the roll 183 in inserting the paper. Since these feed rolls 183, 184, are particularly adapted to feed the paraffin paper, it is desirable that means be provided to free them from accumulations of paraffin or other gummy substances with which the paper may be coated, and to this end each of the rolls is provided with adjustable scrapers, the scraper for roll 184 being indicated by the reference character 193 and comprising a member provided preferably with a sharp edge adjacent the periphery of roll 184 and being provided with suitable longitudinal slots adapted to be engaged by screws 194 by means of which it is adjustably secured to frame 189. Roll 183 is provided with a similar scraper 195 which is adjustably secured to support 173 by similar means as the screws 196 which pass through elongated openings in scraper 195, thereby rendering the same adjustable in relation to support 173 and fixed feed roll 183 carried thereby.

In the various views where shown the reference character 11 is applied to the roll and strip of paraffin paper as well as to the severed paraffin wrappers (see Figs. 19 to 21 inclusive). The roll of paraffin paper on passing downwardly from the roll between the driven feed rolls 183, 184, passes next under spring deflector 197 carried at the end of flexible arm 198 which is secured at its forward end under pivoted guide 199 between which and the plate 200 the paraffin paper is fed to the cutters, where the single stick wrappers are severed. The above parts are shown most clearly in the enlarged sectional views, Figs. 20 and 21, but by an inspection of the plan view of the machine, Fig. 1, it will be seen that on account of the width of the paraffin paper and to secure more perfect control thereof in the passage of the same from the supply roll to the wrapping mechanism the spring deflector 197 is divided or is in duplicate, being secured to upper guide member 199 by screws 201. The lower paraffin paper guide plate 200 terminates adjacent the shear blades which are indicated by the reference characters 202, 203. Adjacent the shear blades 202, 203, the top plate 30 is recessed to permit the free action of the blades forward of the guide member 199 and between the same and the paper shears is the guide plate 204, 130

which is secured to member 199 by screws 205. The guide plate 204 terminates flush with the forward extremity of the lower guide plate 200, being provided with an upturned flange adjacent shear blade 202. The spring deflectors 197 are preferably held down upon the table 30 on top of the paraffin paper strip 11 with only a moderate pressure so that when the feed grippers seize the forward end of the paraffin strip and draw the same forwardly over the folding mechanism, the spring pressed deflectors 197 may be raised from the table as illustrated in Fig. 21, thus giving up a supply of the paraffin paper strip and preventing a too sudden strain upon the paper feed mechanism which is more or less positive, and which might result in the fracturing or tearing of the paper.

Immediately in front of the shears or paraffin paper cutters 202, 203, is the single stick folding mechanism which comprises a suitable folding box formed by a combination of various parts, presently to be described, and over which folding mechanism the forward end of the paraffin strip 11 is adapted to be drawn by the nippers which are situated adjacent the single stick folding mechanism and the construction of which will now be described, (see Figs. 1, 6, 8, 11, 17 and Figs. 26 to 30 inclusive). The paraffin wrapper nippers are carried by a member 206 mounted in a suitable bearing 207 (see Figs. 6 and 11) which is secured to the main frame, as shown by suitable machine screws 208, 209. Secured to member 206 is the upright 210 which may be formed with a lower angular portion for attachment to the under side of member 206 although the preferred construction is that illustrated in which a separate angular member 211 is secured to member 206 and to the vertical leg thereof the upright 210 is secured. Near the upper extremity of 210 is a fixed horizontal plate 212 forming the lower jaw of the nippers. Extending above jaw 212 on each side thereof are ears 213, 214, between which are pivoted on the upper side of plate 212 a plurality of movable nipper jaws 215, the pivot pin being indicated by the reference character 216. There may be any suitable number of these upper pivoted jaws but it is preferred that there be about four, as illustrated, formed each with rearwardly extending portions, preferably much reduced in size as shown and spring tempered in order to be flexible. The two outer pivoted jaws 215 are formed at their rearward extremities with suitable bearing portions as indicated at 217 by which they are secured to a suitable link 218 by pin 219. Link 218 at its other end is pivoted to link 220 by pin 221 and its opposite extremity is pivotally secured to upright 210 at 222. While the two outer pivoted nipper jaws 215 are secured to link 218 by pivot pin 219 as described, it is preferred that the interior pivoted jaws 215 be formed with their rearward flexible extensions plain, as illustrated, and lying loosely upon the pivot pin 219 or the portion of link 218 surrounding said pin. It will be obvious that the construction of the plural nipper jaws is for the purpose of securing the greatest efficiency in the operation of the nippers because it is very essential in the operation of this class of machines that the paper for wrappers and binders shall be firmly gripped and securely held until it is desired that the same be released in the operation of the mechanism. Should there be inequalities in the thickness of the wrappers or should foreign substances accumulate between the nipper jaws rendering one or more of them inoperative, the others may still operate in a normal manner to seize the wrapping material and properly convey the same to the wrapping mechanism. In order to flexibly secure together the interior and exterior pivoted jaws 215 these jaws are provided with apertures between their engaging surfaces and their pivotal connection at 216 and through these apertures which register with each other a pin 223 having a diameter preferably much smaller than these registering apertures is passed. This pin may have its outer extremities formed at an angle, as shown most clearly in Fig. 30, to prevent its becoming disengaged from the jaws and its looseness in the registering apertures in the jaws will permit of a certain amount of independent movement. Movement to the upright 210 carrying the nipper jaws is imparted through reciprocating member 206, link 224 and pivoted arm 225 carried by a projection indicated by reference character 118^a on the under supporting structure 31, the lower end of pivoted member 225 being provided with an antifriction roller in engagement with the suitable cam track on cam 226 carried by counter shaft 113 operated by the main drive shaft 50. With this construction, when the member 206 is reciprocating, upright 210 carrying the nipper jaws, will move from a position adjacent the shear blades 202, 203, having first grasped the free end of the paraffin strip 11 and will draw the same over the single stick folding mechanism, its position at the opposite extremity of its movement being indicated by the view of the same shown in dotted lines in Fig. 26. When the nipper jaws are operated from the position shown in dotted lines in Fig. 26 to the position of these parts indicated in full lines, the jaws are normally open as illustrated, for example, in Fig. 28, they having been opened at the forward extremity of their movement to release the previously cut paraffin wrapper and in this

open position they remain upon being returned to the position adjacent the cutters where they are adapted to seize the free end of the paraffin paper roll.

- 5 It will be noted that the nippers are positioned so that they are adapted to grip one side of the paraffin strip 11 adjacent the end thereof and this feature of construction is of importance because there might be considerable variation in the position of the extreme end of the paraffin roll 11 without causing the nippers to miss grasping the end of the same. The movable nipper jaws 215 being open when they are caused to approach the forward free end of the paraffin roll, as illustrated in Fig. 28, they are then actuated to close and grasp the strip 11 as illustrated in Fig. 27 in the following manner. Pivoted to the under side of table 30 at 227 is a finger 228, the forward extremity of which is adapted to lie under the pivoted links 218, 220, when the nippers are brought to the position ready to receive the free end of paraffin strip 11. At this instant the finger 228 is operated to the position shown in Figs. 26 and 27, causing the nipper jaws 215 to close upon and bind the strip 11 between them and the under jaw or plate 212. The pivoted finger 228 is operated through member 229 with which it is pivotally connected at 230, member 229 being provided with an anti-friction roller 231 in engagement with a suitable cam track on the cam 232, which is mounted to rotate on countershaft 102 (see Figs. 6 and 11). After being operated by the finger 228 to close upon the forward end of the paraffin strip, the nippers are then operated by the mechanism described to draw the paraffin strip over the folding mechanism to the position shown for example in Figs. 20 and 21, which brings the paraffin wrapper immediately over the single stick folding box. The shear blades 202, 203, are now operated to sever the single stick paraffin wrapper from the strip 11, and a single stick of gum having been discharged from the gum magazine and impaled upon the gum picks 164 immediately over the folding mechanism, 50 the plunger 162 carrying the gum picks is then lowered by the downward movement of shaft 166 which presses the single stick of gum 10 into the single stick folding box at the same time forcing the cut paraffin wrapper into the folding box with the single stick of gum and folding the longitudinal sides of the cut paraffin wrapper 11 to the vertical position, as illustrated in Fig. 43. This downward movement of vertical shaft 166 carrying the gum picks also depresses a finger 233 secured thereto (see Figs. 11, 26 and 28) which, being in position to contact with links 218, 220 controlling nipper jaws 215, depresses these links in the manner shown 65 in Fig. 28, thus causing the nippers to re-

lease the cut paraffin wrapper at the instant the single stick of gum is forced on top of the paraffin wrapper and into the folding box. It is in this position that the nipper jaws are returned to their initial position 70 adjacent the free end of the paraffin strip 11 to engage the same and draw it forwardly over the folding box to be severed and form the succeeding single stick wrapper. To the upright member 210 carrying the nipper 75 jaws is adjustably secured to plate 234 by screw 235, which plate checks the upward movement of links 218, 220, as they pass beyond the center to lock the gripper jaws in closed position and by adjusting this plate 80 234, the degree to which the pivot pin 221 may pass upwardly beyond the line joining pins 219 and 222 may be accurately determined and which will also determine the degree of pressure with which the jaws 212, 85 215 may be caused to grip the paraffin wrappers.

The mechanism for operating shear blades 202, 203, will now be described. (See Figs. 1, 6 and 17). These shear blades are pivotally connected at 236 and supported on the upper extremity of member 237 secured to top plate or table 30. At the lower extremity of member 237 is pivoted bell crank 238 at 239. Pivoted connected to the vertical arm of bell crank 238 at 240 are links 241, and 242, which are pivotally connected with extensions on blades 202, 203, beyond their pivotal connection 236. Bell crank 238 is rocked on its pivot 239 to cause blades 100 202, 203 to open and close by reciprocating member 243 provided with anti-friction roller 244 engaging a suitable cam track on cam 245, which is carried by and rotates with shaft 70 heretofore described. The reciprocating member 243 may be supported at its end adjacent the cam 245 in any desired manner, the preferred form being that shown in Fig. 17 in which the member is bifurcated and branches thereof supported by shaft 70. This is a simple and economical construction and is employed to an extent throughout the entire construction of the machine, as, for example, for supporting the extremity of reciprocating member 229 110 adjacent its operating cam 232 (see Fig. 11). 115

The folding box or mechanism for folding cut paraffin wrappers around the single sticks and the further operation of wrapping the single sticks will now be described. (See Figs. 1, 6, 8, 12, and Figs. 41 to 49 inclusive). The folding box for the single sticks is comprised of only approximately parallel side members and a bottom member, the ends of the folding box being open and consequently the ends of the single stick package are crimped and folded after the partially wrapped stick leaves the folding box. Secured to top plate or table 30 is a stationary plate 246 which may, if desired, 120 125 130

be formed as an integral part of top plate 30. Adjacent the forward edge of stationary plate 246 and immediately under the gum picks the single stick folding box is located, the forward side being formed by spring controlled vertically movable plate 247 and the rear side thereof by pivoted member 248. The member 248 comprises a flat strip provided with one or more notches, 5 as indicated at 249, for the purpose of registering with the gum picks 164 (see Figs. 44 and 45). The rear folding member 248 is provided with two downwardly extending branches which support the rear side folder 10 carried at the upward extremity thereof (see Figs. 6 and 8) and are pivotally secured on shaft 70, each branch extending from its pivotal connection with shaft 70 forwardly and downwardly and being provided 15 at their lower extremities with suitable rollers in engagement with cam tracks on cams 67, 69, rotatably secured to main drive shaft 50 at the front side of the machine. By this construction the rear side folder 248 will be operated to and fro over the rear side of the folding box to the extremes indicated in Figs. 41 and 44 respectively. The forward single stick side flap folder, unlike the rear side flap folder 248 20 just described is stationary with respect to the folding box except that it has a vertical movement under the control of compression spring 250 on upwardly extending member 251 which bears against the top of member 247 and has a loose connection with an overhanging arm on member 252 which is pivotally secured at 253 to a suitable bracket 254 on top plate 30. This construction permits of a limited amount of movement between forward side folding member 247 beneath which and the fixed plate 246 on top plate 30 the single sticks of gum are passed after being discharged from the folding box already described whereby the side flaps are 30 first folded to the vertical position as illustrated in Fig. 43 and subsequently the rear side flap is folded flat upon the single stick of gum, as illustrated in Fig. 44, this operation being illustrated in Fig. 45. In the 35 operation of the machine it is found frequently desirable to remove the front side flap folder plate 247 which is accomplished by operating member 252 on its pivotal connection 253 with the bracket 254 and to this end the operating member 252 is provided with an upwardly projecting portion adapted to be grasped by the hand of the operator. Pivoted to the operating member 252 is a hand lever 255 having a short projection 256 40 engaging one end of a latch 257 pivoted on member 252 at 258. The lower extremity of latch 257 is adapted to engage a notched member 259 preferably secured to bracket 254. When the latch 257 is in engagement 45 with the notch on member 259 the forward side folder plate 247 will be held downwardly toward plate 246 under the elastic tension of compression spring 250. On the other hand, when the operator desires to remove the forward side folder plate 247 for the purpose of cleaning the device or for any other purpose the hand lever 255 may be operated to release the latch 257 and the supporting member 252 may be rocked on its pivotal connection to release the forward 50 side flap folder plate 247.

The bottom of the single stick folding box into which the gum is introduced by the gum picks on plunger 162 consists of a member 260 secured to the upper extremity of a cross head 261 by which it is adapted to have vertical movement between the limits indicated by the relative positions of the parts as shown in Figs. 41 and 42. Cross head 261 is supported at the top of vertically reciprocating member 262 (see Fig. 12) which is bifurcated at its lower extremity to slide over shaft 70 and is provided with a suitable roller 263 engaging with a suitable cam track in cam 264 secured to and rotating with shaft 70. Cross head 261 carrying the member 260 is provided with two downwardly projecting guide pins 265, 266, adapted to slide in suitable ways in guide brackets 267, 268, which are secured to the top plate 30. By this construction the bottom member 260 of the folding box is moved to the upper limits of its movement, as illustrated in Fig. 42, the cut paraffin wrapper 11 having been previously brought to position over the folding box and the plunger 162,—carrying the gum sticks with the single stick of gum 10 impaled thereon,—then moves downwardly, binding the stick 10 and the paraffin wrapper 11 between the gum picks and the member 260, both paraffin wrapper 11 and gum stick 10 being held considerably above the top of the folding box. At this instant the member 260 under the control of cam 264 is moved downwardly until the parts are in the relative position shown in Fig. 43 with the longitudinal side flaps of the paraffin wrapper 11 brought to the vertical position by contact with rear side flap folder 248 and stationary front folder plate 247. During the downward movement of the member 260 the gum picks 164 on plunger 162 follow the downward movement so that the relation of these parts and the gum stick and the wrapper are not disturbed. 100

The upper surface of member 260 at the bottom of the single stick folding box immediately underneath the gum picks 164 is slightly depressed as indicated at 260^a (see Fig. 31) to prevent the possibility of the gum picks being injured by striking the surface of the bottom of the folding box. The rear side flap folder 248 is now actuated to move forwardly by cams 67, 69, folding the 105 110 115 120 125 130

rear side flap downwardly and bringing the parts to the relative positions illustrated in Fig. 44. The vertically reciprocating member 260 forming the bottom of the folding box is provided with two slots as indicated at 269 (see Figs. 12, 20 and 21) and into these slots project at the rearward limits of its movement, the rear ends of single stick transport 270 (see Fig. 12, also Figs. 42 and 44). The details of construction and mode of operation of this single stick transport 270 is further shown in Figs. 8, 13 and in the detail views shown in Figs. 31, and 37 to 40 inclusive, from an inspection of which it will be seen that it is comprised of two parallel plates joined together by suitable cross connections at the connecting plate 271², as indicated at 271, and provided at their upper extremities with a plurality of space indentations, as indicated at 272, said indentations being in length approximately the width of a single stick of gum and in depth a little more than the thickness of the single stick. The plates 270 are provided on their interior surfaces with opposing grooves as indicated at 273, which take plate 274 which is carried at the top of shaft 275, being secured thereto by machine screw 276. The shaft 275 is supported to reciprocate in suitable bearing 277, secured to top plate 30, and is preferably bifurcated as shown at its lower extremity and inserted over shaft 71 to form a bearing and permit longitudinal movement of the shaft and the plate 274 and associated parts which is accomplished through anti-friction roller 279 operating in the regular cam slot as indicated at 280 in cam wheel 281 which is secured to rotate with shaft 71. One of the side members 270 of the single stick transport is provided with a number of somewhat elongated vertically extending teeth as indicated at 282 (see Figs. 39 and 40). In mesh with teeth 282 is a segmental gear 283 pivoted to the top plate 30 at 284 and being provided with an extension to which is pivoted at 285 a pitman 286 (see Figs. 6, 13, and 39). At the opposite end of pitman 286 the rocker arm 287 is loosely secured by being sleeved over the end of the rod between adjustable nuts 288, 289. To cushion the transport mechanism and provide against sudden shocks from the operating mechanism the spring as indicated at 290 may be interposed between nuts 289 and the upper extremity of rocker arm 287, which is pivoted at 291, to the under frame structure 31 and a depending portion provided with a suitable roller 292 in engagement with a cam track in cam 293 on counter shaft 113 which is driven as described from main drive shaft 50 and through which means reciprocation is imparted to the single stick transport 270. It will be seen that the elongated teeth 282 in mesh with segmental gear 283 will permit

vertical movement between the transport 270 and the gear 283 when the transport is operated as described under control of vertically reciprocating shaft 275. By this construction it will be seen that the single stick transport 270 has a four-way movement, its vertical reciprocation being under the control of shaft 275 and its longitudinal reciprocation being under the control of segmental gear 283. In the operation of the single stick folding mechanism at the instant that the rear side flap folders 248 advances to fold the rear side flap of the single stick paraffin wrapper 11 (see Fig. 44) the transport 270 is raised vertically so that the rearmost recess 272 in the top edges thereof engages the partially wrapped single stick whereupon the segmental gear 283 is rocked to move the transport forwardly carrying the single stick partially wrapped package under spring plate 247 and folding down flat upon the forward side of the package the forward side flap, as illustrated in Fig. 45, the wrapped single stick then assuming the form shown in Fig. 46. The stationary plate 246 between which and the spring plate 247 the partially wrapped single sticks are now passed, is fixed in relation to top plate 30 of the machine by being secured to and extending rearwardly from the angular cleat 294 being secured thereto by screw 246^a and cleat 294 is bolted to top plate 30 at 295. Cleat 294 is provided with an upturned flange as indicated at 296 which co-operating with the forward extremity of spring pressed plate 247 preferably provided with an upturned flange as indicated at 297 forms an accumulating chamber as indicated at 298 into which the wrapped single stick packages are discharged from the single stick transport 270 whence they are transferred in multiple quantities, as hereinafter described, to other parts of the machine to be wrapped in multiple stick packages.

During the transit of the single stick package from its position in the single stick folding box, as shown for example in Figs. 44 and 45, to its position in the single stick accumulating chamber 298 under the control of the single stick transport 270 the ends of the paraffin wrappers on the single sticks are folded flat upon the under side of the single stick packages, as illustrated in Figs. 46 to 48 inclusive, a completely wrapped single stick being shown in Fig. 48, by the following described means (see Figs. 31 to 35 inclusive). Immediately the single sticks are carried by transport 270 from the single stick folding box, being held in the depressions or spaced indentations 272, the ends of the paraffin wrapper are passed under initial end folders 299, 300, (see enlarged detail of one of these folders, Fig. 34). The ends of the paraffin wrapper con-

tacting with the inclined surfaces on folders 299, 300 will be first folded to the vertical position as illustrated in Fig. 32. As the sticks are carried farther forward, the 5 downwardly extending vertical ends of the wrapper will next pass through the angular slots, as indicated at 303 and 304 in final end folding members 301, 302, (see Figs. 33 and 35). Secured to the forward extremities of the single stick transport 270 are blocks as indicated at 305, 306, for the purpose of widening the upper bearing surface of the transport adjacent the single stick accumulating chamber. At their rearward extremities, as indicated at 307, 308, the blocks 305, 306 are beveled as shown in Fig. 31, so that they will not present a sharp edge which might injure the folded ends of the folded paraffin wrappers as they are 10 passed to the accumulating chamber. The initial single stick and folders 299, 300 are secured to top plate 30 by screws as indicated at 309 and 310, and the final end folders 301, 302, are secured as indicated at 15 311, 312. It will be noted that the indentations in the single stick transport 270 which receive and feed the single sticks forwardly from the single stick folding box to the accumulating chamber 298 are evenly spaced 20 from front to rear, which is essential to the proper operation of the device as its horizontal reciprocatory movement is equal to the distance between each of these spaces, the action of the transport therefore being 25 30 to receive the partially wrapped single stick from the single stick wrapping box and to convey the same forwardly and under spring pressed plate 247, a distance equal to the distance between the first indentation 35 40 272 and the second of such indentations. The transport will then be drawn downwardly, depositing the partially wrapped single stick on top of fixed plate 246 after which it will move rearwardly as described, 45 to a distance equal to the distance it previously moved forwardly, thence it will be moved upwardly to its initial position as shown, for example, in Figs. 44 and 45 and will engage the succeeding partially wrapped 50 single stick in the folding box and the previously described operation will then be repeated.

It should be observed that when the transport 270 was depressed in the operation just described, it deposited a partially wrapped single stick between the plate 246 and spring plate 247, which partially wrapped stick is engaged by the second depression 272 on the next succeeding upward movement of the 55 single stick transport. In the same manner it will be seen that at each four-way movement of the single stick transport, each of the wrapped or partially wrapped single sticks carried thereby will be advanced forwardly under spring pressed plate 247, a

distance equal to the common distance between each of the feed depressions 272, and finally the single sticks with the paraffin wrappers thereon coming from the single stick folding box will be advanced to a position immediately below the single stick accumulating chamber 298 and during this progress from the folding box to the accumulating chamber, the ends of the paraffin wrapper 11 will have been folded flat 70 upon the under side of the package, with the package resulting in the form illustrated in Fig. 48. From an inspection of Figs. 41 to 49 inclusive, it will be seen that the forward depression 272 in the single stick 75 transport 270 cooperates directly with the accumulating chamber 298 delivering each singly wrapped stick thereto, then withdrawing which causes the forward extremity of the transport where widened by the 80 addition of blocks 305, 306, to drop below the level of stationary plate 246 forming the bottom of accumulating chamber 298 (see Figs. 31, 37 and 38). When a plurality of singly wrapped sticks have been delivered 85 by the multiple stick transport into the accumulating chamber 298, that is to say, the number of singly wrapped sticks desired to make up a complete multiple stick package, which is usually five sticks, mechanism 90 is provided for delivering these singly wrapped sticks in predetermined multiple quantities to a suitable transport which carries this multiple quantity of sticks to the foil wrapping mechanism. This multiple stick delivering means will first be described.

Journalized over shaft 275 and adapted to reciprocate thereon is block 313 to which is secured uprights 314, 315, the upper extremities of which extend adjacent the multiple stick accumulating chamber 298 adjacent each end thereof. These uprights are secured to the block 313 by the machine screws 316, 317, and are further secured, if 105 desired, by a plurality of pins as indicated at 318. Uprights 314, 315, are slotted vertically at 319, 320, which slots are adapted to furnish a sliding support for package hooks 321, 322, which are provided with 110 the inwardly projecting pins 323, 324, near the bottoms thereof and with the longer rigid pins 325, 326, near the middle portions thereof which are adapted to contact at certain times with the cam surfaces 327, 115 328, on the sides of the multiple stick transport 270 near its forward extremity (see Figs. 37 and 38).

The block 313 carrying the above described mechanism although mounted for 120 support to reciprocate on shaft 275 as described is supported by downwardly extending member 329 which is adapted to be driven from cam 330 on shaft 71, this cam being provided with a suitable cam track 125 130.

adapted to take an anti-friction roller 332 (see Fig. 37) on the lower extremity of member 329. The block 313 is further supported by being journaled to reciprocate on pin 331 parallel with shaft 275 and fixed to support 277 secured to top plate 30. Package hooks 321, 322, are secured in position at their lower extremities in slots 319, 320 on uprights 314, 315, by clips 333, 334 which are also secured in position by screws 316, 317, which also secure the uprights 314, 315, in position as described. By this construction it will be seen that the uprights 314, 315, have a reciprocatory movement in a vertical plane and the package hooks 321, 322, normally carried thereby are capable of independent movement in relation to uprights 314, 315, under control of tension springs 335, 336, secured to block 313 by the common eye-bolt 337 and being connected with these package hooks at the hooked extremities of members 338, 339, which extend inwardly through slots 319, 320. These package hooks are provided at their upper extremities with the inwardly extending projection as indicated at 321^a, 322^a. By referring to detail plan view of the single stick accumulating chamber 298 shown in Fig. 31, it will be seen that uprights 314, 315, have their upper extremities extending along the forward extremity of transport 270 and are adapted to receive the wrapped single sticks as they are delivered by transport 270 into the accumulating chamber, and they support the single sticks within the accumulating chamber when the single stick transport 270 withdraws from the single sticks by being depressed in the manner heretofore described. The package hooks 321, 322 with their inwardly projecting extensions 321^a, 322^a, normally rest near the top of supports 314, 315, being held downwardly under the action of springs 335, 336, but as the single stick transport delivers the wrapped single sticks to the accumulating chamber, these package hooks are gradually lifted by the pressure of the sticks themselves, thus automatically enlarging the chamber to accommodate the required number of wrapped single sticks to make a completed package. When the required number of wrapped single sticks, usually five, have been received in the accumulating chamber, block 313 with its associated parts is raised vertically through its actuating mechanism, as described, carrying upwardly the upright supports 314, 315, lifting the wrapped single sticks within the accumulating chamber above the top of the flanges 296, 297, thereof (see Fig. 50), thus clearing the package above the top of the accumulating chamber in order that it may be freely grasped by the multiple stick transport or carrier for delivery to the foil wrapping mechanism.

At the instant the multiple stick transport receives the plurality of wrapped sticks from the accumulating chamber 298, the single stick transport 270 has been reciprocated to its position nearest the front of the machine or in the direction of the gum magazine, thus causing cams 327, 328, on the forward end of the transport to engage pins 325, 326 on the package hooks 321, 322, which will spread these hooks beyond the ends of the package and allow the same to be freely lifted from the end of supports 314, 315, for delivery to the foil wrapping mechanism. When the multiple stick package has been received by the pivoted transport or carrier the block 313 carrying supports 314, 315, and associated mechanism is depressed by its actuating mechanism and the transport 270 having been actuated forwardly to convey other single sticks to the accumulating chamber, the cams 327, 328, will at the same time have cleared pins 325, 326, on the package hooks 321, 322, and these hooks will then resume their normal position in relation to uprights 314, 315, and these parts will then be in normal position ready to receive a succeeding accumulation of single sticks wrapped with the paraffin wrappers.

The multiple stick transport or carrier for conveying the singly wrapped sticks in predetermined quantities from the accumulating chamber 298 to the foil wrapping box will now be described. (See Figs. 1, 4, 5, 13 and 36). 340 is a rock shaft journaled in the under supporting structure 31 immediately below top plate 30 and is provided with an arm 341 to which is pivotally connected at 342 a pitman 343, the lower extremity of which is bifurcated and for a support the bifurcated portion is adapted to slide over its actuating shaft 72 to which is keyed cam 344 provided with a suitable cam track as indicated in dotted lines in Fig. 36 which is engaged by anti-friction roller 345 secured to pitman 343. The rock shaft 340 carries an arm 346 which is loosely journaled thereon but caused normally to be rocked thereby by means of a plunger 347 contained in casing 346^a controlled by spring 347^a, the plunger 347 being adapted to engage a flattened portion on rock shaft 340. This connection between arm 346 and its actuating shaft is provided as a safety precaution, the action of the spring pressed plunger on flattened rock shaft 340 being sufficient to cause the arm 346 to be rocked when the machine is operated normally but should there be an accumulation of sticks of gum or other material either in the accumulating chamber or in the foil wrapping box sufficient to clog the multiple stick transport or carrier, the rock shaft 340 may operate independently against the action of the spring pressed plunger 347 and the arm 346

will remain in a temporary fixed position, thus obviating the danger of breakage of the parts. The multiple stick transport or carrier proper is composed of a suitable irregular plate 348 to which arm 346 is pivotally connected at 349. This plate is also pivotally connected at 350 to link 351 which has pivotal connection at its lower extremity as indicated at 352, with branch 358 on casting 354 which also provides a bearing for rock shaft 340 and is secured to the under side of top plate 30, as illustrated in Fig. 13. Plate 348 is provided with two downwardly projecting fingers 355, 356, which may be formed integrally with this plate, as shown and cooperating with fixed fingers 355, 356, are the opposing fingers 357, 358, loosely mounted on pins 359, 360, fixed in the forward edge of plate 348. Between the heads of pins 359, 360 and opposing fingers 357, 358, are compression springs as indicated at 361, which are compressed when the fingers 357, 358, are moved apart from stationary fingers 355, 356, thus causing the plurality of single sticks of gum within the multiple stick carrier or transport to be held under elastic tension. The fixed fingers 355, 356, as well as the spring controlled movable fingers 357, 358, are provided at their lower extremities with slight projections as indicated in the drawings which prevent any possibility of the sticks of gum accidentally falling from the carrier in transit. Also secured to the plate 348 between the spring controlled fingers 357, 358, is an angular clip 362 having a downwardly projecting portion somewhat beveled, as illustrated in Figs. 50 and 51. This clip is fixed to plate 348 by a screw or other suitable means as indicated at 363 and the bevel downwardly projecting portion intersects the normal plane of the spring controlled fingers 357, 358, and assists in retaining in fixed position particularly the upper sticks in the multiple stick package which on account of the normal angularity of the spring controlled fingers 357, 358, with respect to the fixed fingers 355, 356, are not positively engaged between the fingers of the carrier, the multiple stick carrier or transport having grasped the plurality of wrapped single sticks contained within the accumulating chamber in the manner described and as illustrated particularly in Fig. 50, is then moved by its parallel link movement, in the manner already described, to the position indicated in Fig. 57, immediately above the foil wrapping box (see Fig. 51).

The construction and operation of so much of the mechanism as pertains to the bringing of the predetermined number of single sticks, each covered with its paraffin paper wrapper, to the foil wrapping box, having been described, the foil wrapping mechanism will now be described (see Figs.

2, 7, 9, 14, 15, 16, and 50 to 64 inclusive). A plan view of the foil folding box and the foil wrapping mechanism is shown in Fig. 63. Immediately below the point of delivery by the multiple stick carrier to the foil folding box, the top plate 30 is cut away. The foil folding box (see Fig. 51) consists of a relatively stationary forward side flap folding member, a movable rear side flap folder and a vertically movable bottom member. The forward edge of the movable plate 364 is beveled as indicated at 365 and constitutes the forward longitudinal side of the foil folding box. This plate is provided with downwardly extending flanges along its sides between which the packages after having the foil wrapper partially applied in the foil folding box are passed. But it is loosely mounted over such passage and vertical movement thereof is permitted under the control of pin 366 resting upon the top thereof and pressed downwardly by coil spring 367 interposed between a washer 368 secured near the lower extremity of this pin, and the arm 369 supported on top plate 30. By this construction the plate 364 is normally pressed downwardly under control of spring 367 but will lift vertically to accommodate packages of varying thicknesses. Arm 369 is carried on top plate 30 by means of the upright 370 and is secured in position by machine screw indicated at 371 (see Fig. 2). The rearward side of the foil folding box consists of the movable folding member 372 supported at each end by the pivoted uprights 373, 374, which extend downwardly and toward the front of the machine being pivoted on shaft 72 (see Figs. 7 and 14) and being provided at their forward extremities with suitable anti-friction rollers engaging cam tracks in cams 375, 376, which are secured to rotate with shaft 71 in the under structure of the machine (see Fig. 6). The rear side flap folding member 372 is angular in form, as may be seen by an inspection of Fig. 52 and adjacent its forward folding edge it is provided with an upwardly extending flanged portion, as indicated at 377, which is beveled somewhat similarly to the beveled folding edge 365 on spring pressed plate 364. This construction of the two parts constituting the longitudinal sides of the folding box enables the multiple stick carrier mechanism to approach more nearly the bottom of the folding box in depositing the package of single wrapped sticks and this construction further is advantageous in that no sharp corners are presented to the foil wrapper in the folding operation, which might tend to tear the foil and spoil the package. The folding member 372 is also provided near its extremities with angular ribs 378, 379, for the purpose of assisting in the operation of

folding the ends of the foil wrapper, as will be presently described. The folding member 372 is also provided along its folding edge with recesses as indicated at 380, 381, 5 adapted to register with blunt pins 382, 383, which are carried by the vertically movable arm 384. This arm is secured on vertically reciprocating member 385 by set screw 386, member 385 extending downwardly and provided with a suitable bearing as indicated at 387, and having near its lower extremity an anti-friction roller 388 in engagement with a suitable cam track in cam wheel 389 which is mounted to rotate with shaft 72. 10 The blunt pins 382, 383, are operated by the mechanism just described to descend upon the top of the foil wrapping box, as indicated, for example, in Fig. 51, following the delivery to the foil wrapping mechanism of a quantity of wrapped single sticks, a foil wrapper as indicated by the reference character 12 having been previously placed in position over the folding box, as illustrated in Fig. 51. The multiple 20 stick carrying device is constructed so as to permit the pins 382, 383, to descend through suitable cut away portions in plate 348 to the top of the package of single sticks and by continuing their downward movement 25 they discharge the wrapped sticks downwardly into the foil wrapping box, as illustrated in Fig. 51, at the same time folding the longitudinal side flaps of the foil wrapper 12 to the vertical position, as shown in 30 Fig. 52. As soon as the multiple stick package has been discharged from the carrying device by pins 382, 383, the carrier is operated to its original position in the manner described, which original position is 35 illustrated in Fig. 50 to receive a succeeding package of wrapped single sticks. Constituting the bottom of the foil wrapping box is the vertical moving plunger 390. The top of plunger 390 is provided with a slot as 40 indicated at 391 adapted to receive the rear end of foil wrapper transport 392, (see Fig. 63). The plunger 390 is secured to the top of cross head 393 which is provided with the fixed downwardly extending pins 394, 45 395, carried in bearings on bracket 396, secured to the under side of top plate 30 (see Fig. 9). Cross head 393 carrying plunger 390, is provided with a downward extension as indicated at 397 carrying at its lower 50 55 extremity an anti-friction roller 398 engaging a suitable cam track 399 on cam 400, which is secured to rotate with driving shaft 72. By this construction the plunger 390 in the bottom of the foil wrapping box is 60 actuated in a vertical plane through the limits of movement, as indicated in Figs. 51 and 52, first to its extreme upward position, as shown in Fig. 51, where it is flush with the top of the foil wrapping box and 65 is then depressed to the position shown in

Fig. 52 as the multiple stick package is pressed downwardly under pressure from pins 382, 383, to fold the side flaps of the foil wrapper to the vertical position, the foil wrapper being held firmly between the 70 multiple stick package and the top of plunger 390, and preventing the shifting of the foil wrapper out of proper relation with the multiple stick package during the folding operation. Pins 382, 383 are loosely 75 mounted on arm 384 and have a limited amount of movement in relation thereto to accommodate them to different thicknesses 80 of the package under control of elastic means, as springs 401.

In the preceding description of the foil wrapping mechanism the foil wrapper 12 has been referred to and a description of the means employed in positioning this wrapper with respect to the multiple stick package in the folding mechanism will now be given, (see Figs. 2, 9 and 14). At the extreme right hand side of the top plate 30 is a flanged reel 402 for supporting a roll of foil consisting of a continuous web or strip. 85 This wheel is supported on a pin mounted in an upright as indicated at 403. Below the reel 402 are two coöperating rolls 404, 405, which are geared to rotate together and between which the strip of foil is adapted 90 to pass from the reel 402, one of said rolls being mounted on a shaft which is extended through a bearing on upright 403 and provided with a suitable sprocket wheel adapted 95 to be driven by a sprocket chain 406 (see 100 Fig. 2) which passes over driving sprocket 112 on the counter shaft 103 in the under structure of the machine (see Fig. 7). This mechanism for feeding the foil wrappers to the foil wrapping mechanism and for cutting them is a duplicate of the mechanism already described in detail for feeding the paraffin strip and severing the wrappers therefrom to the single stick wrapping mechanism, as illustrated, for example, in 105 Figs. 18 to 30 inclusive, and already described in detail and hence a further detail description is omitted except to notice that the foil strip on passing downwardly between the positively driven feed rolls 404, 405 passes under the spring pressed plate 110 115 407 (see Fig. 14) and between guide plates 408, 409, where the forward end of the foil strip is engaged by the foil gripper jaws and drawn forwardly over the foil wrapping box to the position illustrated in Fig. 51. The gripper jaws 215 (see Fig. 9) are 120 preferably a duplicate of the gripper jaws already described in detail for conveying the paraffin wrappers to the single stick wrapping mechanism (see Figs. 26 to 30 inclusive), being actuated to close the jaws on 125 the side of the foil strip near the forward end by a mechanism similar to that shown in Fig. 26 a portion of such mechanism being 130

- shown in Figs. 7 and 9, the reciprocating member 229^b corresponding to member 229 and being actuated by cam 232^b corresponding to cam 232. The jaws are actuated 5 to open to release the foil wrapper after it is placed in position over the foil wrapping box and cut by shear blades 411, 412, by a fixed finger as indicated at 413 which is secured on the vertically reciprocating shaft 10 385, (see Figs. 5 and 14). The construction and operation of this finger 413 is identical with that of the finger 233 already described and as illustrated in Figs. 26 to 28 inclusive. The foil gripper jaws 410 are supported by 15 member 414 (see Figs. 7 and 9) which is carried by member 415 mounted on the under side of top plate 30 and supported to reciprocate longitudinally by an elongated bearing as indicated at 416 which is secured 20 to the under side of top plate 30. Movement is imparted to member 415 by means of a link 417 pivotally connected to the upper extremity of rocker arm 418 which is pivotally supported on bracket 419, being 25 an integral part of under structure 31. The lower extremity of the rocker arm 418 is provided with a suitable anti-friction roller (not shown) which is in engagement with the cam track on the cam wheel 420, this 30 cam wheel being keyed to counter-shaft 114 which is operatively connected with driving shaft 71 (see Fig. 6).
- The transport 392 adjacent the foil wrapping box has already been referred to and 35 from an inspection of the views of the same in Figs. 9, 62 and 63, it will be seen that it consists of an irregular casting provided with a downwardly and rearwardly extending portion and that this lower rearwardly extending portion is provided with an opening by which the transport is carried by and adapted to reciprocate on horizontal link 421 which is supported near its extremities by having pivotal connection with 40 links 422, 423, which last said links are supported by having pivotal connection with suitable depending lugs on top plate 30, one of such lugs being indicated by the reference character 424 (see Figs. 9 and 45 64). Member 421, supporting transport 392, is rocked on links 422, 423, through link 425 which is connected to the upper extremity of rocker arm 426 pivotally connected to bracket 427 on under structure 31 50 of the main frame, the lower extremity of this rocker arm being provided with the usual anti-friction roller in engagement with cam track 428 on cam wheel 429 which is keyed to driving shaft 74.
- 55 It will be seen that by the mechanism just described, the transport 392 will be moved in a vertical plane by the rotation of cam 429, as illustrated in Fig. 64. It is desirable that this transport have a four-way movement and provision is made for reciprocating 60 the same horizontally on the supporting bar 421 by means of link 430 which is pivotally connected to the upper extremity of the rocker arm 431 carried by bracket 427 on under structure 31 and being provided at its lower extremity with an anti-friction roller engaging cam track 432 on cam wheel 433 on shaft 74. The upper surface of the transport 392 is provided with two transverse slots as indicated at 434, 435. In Fig. 53 transport 392 is shown in its rearmost position with the feed slot 434 registering with the foil wrapping box, the pins 382 having descended and forced the package to the bottom of the wrapping mechanism, bringing the side flaps of the foil wrapper 12 to the vertical position. In this view, the rear side flap folder 372 is shown actuated to the position over a portion of the top of the package, thus folding down flat the rear flap and at the same time the ends of the foil wrapper at the rear side have been indented or creased as indicated at 12^a in Fig. 55 by the contact of the angular ribs 378, 379. At this instant the transport 392 is operated through link 430 and rocker arm 431 toward its forward position as illustrated in Fig. 56, thus folding the forward side flap of the foil wrapper down flat on the upper side of the package by reason of its contact with the beveled under surface of the forward edge of spring pressed plate 364. In Fig. 56 the transport 392 is shown as almost, but not quite, 100 at the limit of its forward movement, where the package is carried to a position immediately beneath the end crimpler members which consist of the two branches 436, 437, (see also Fig. 15), preferably formed integrally with arm 438, which extends horizontally from shaft 439 reciprocating in bearing 440 carried by top plate 30 and adapted to be actuated by cam wheel 441 on shaft 73. The lower extremities of end crimplers 436, 437, are provided with depending angular folding ribs as indicated at 442, 443, similar in shape to the angular ribs 378, 379, already described, on the rear side flap folder 372. These ribs 442, 443, 105 have a like purpose, viz., they are interposed as shown in Fig. 56, in the path of the foil wrapped package as it is passed under spring pressed plate 364 into position immediately under end crimplers 436, 437. These end crimplers 436, 437, normally rest in the position illustrated in Fig. 56, the depending portions 442, 443, 110 only being interposed in the path of the incoming package and as the package is fed into its normal position immediately under end crimplers 436, 437, the ribs 442, 443, 115 will indent the sides of the package near each end thereof at the forward side, as also indicated by the reference character 120 125 125 130

12^a, in Fig. 58, such indentations being opposite the indentations 12^a previously put in the ends of the foil wrapper, as already described, by the rear side flap folder 372 and the angular ribs 378, 379, carried thereby. When the package is in normal position immediately underneath the end crimpers 436, 437, the ends near the forward side having been indented at 12^a by the angular ribs 442, 443, the end crimping device is then lowered by cam 441 acting upon shaft 439 which will cause the end crimpers 436, 437, to contact with the ends of the foil wrapper crimping the ends of the foil wrapper and folding them downwardly as illustrated in Fig. 59. In order that the end crimpers 436, 437, may have free access to the ends of the foil wrapper protruding beyond the wrapped sticks in the package, top plate 30 is cut away as illustrated in Fig. 63, there being recesses provided in the plate as indicated at 444, 445, adapted to clear the ends of the crimpers when they descend. By an inspection of Fig. 63 in particular it will be seen that the plate 30 is also cut away some distance from the sides of the transport 392 and a portion of the space thus remaining between the transport and the plate is filled by detachable wearing strips 446, 447, which are secured to the top plate 30 by suitable screws as indicated, thus rendering them detachable for the purpose of renewing them when they become worn. It will be noted by an inspection of Fig. 63 that leading from the recesses 444, 445, in the top plate which register with end crimpers 436, 437, there are slots provided between the top plate and the wear strips 446, 447, as indicated by the reference characters 448, 449, which slots lead to the end folding means and permit the vertically folded and crimped ends of the foil wrapper as illustrated in Fig. 59 to be transported in that position to the end folding means which comprises reciprocating plates 450, 451, (see Figs. 60 and 63) which are mounted to reciprocate in suitable grooves provided in the upper surface of top plate 30 and retained in position by detachable cross bars 452, 453, which are secured to top plate 30 by suitable screws as illustrated. From the above description, the operation of the end folders 450, 451, will be obvious, since the ends of the foil wrapped package after being crimped downwardly, as illustrated in Fig. 59, will slide through slots 448, 449, as the feed slot 435 in the transport 392 engages the package and carries it rearwardly to a position immediately over end folders 450, 451. It will be seen that the strips 446, 447, on either side of the transport 392 will serve the purpose of supporting the foil wrapped package as it is transported through the foil wrapping mechanism underneath spring pressed plate

364. The end folders 450, 451 are mounted to reciprocate in suitable grooves on top plate 30 and are actuated toward and from each other in the operation of folding crimped end flaps of the foil wrapper by the depending ears 454, 455, which are pivotally connected to rocker arm 456, the depending member 455 being directly pivoted at the top thereof and the depending member 454 being connected near the bottom thereof through the intermediate pivoted link 457. The rocker arm 456 is pivotally supported by bracket 458 secured to top plate 30 and is provided with a downward extension below the pivotal connection therewith of the link 457 and to this extension is pivotally connected a link 459 connected with the upper extremity of rocker arm 460 having pivotal connection with the under structure 31 at 461 and provided at its lower extremity with anti-friction roller 462 engaging cam track 463 in cam wheel 464 which is keyed to counter shaft 114 by which it is operated. By an inspection of Fig. 63 it will be seen that just forward of the end folders 450, 451, the members 446, 447 are provided with converging beveled surfaces as indicated at 465, 466, which are provided for the purpose of gradually pressing upwardly the folded end flaps of the foil wrapped package immediately after leaving the end folders because it is found in practice that the elasticity of the material comprising the foil wrapper may cause the ends to slightly open up and should they do so the beveled converging surfaces 465, 466, will present no abrupt edges which might result in tearing or otherwise injuring the package or the wrapper.

Before finally passing from the description and mode of operation of the foil applying and wrapping mechanisms, it may be noted that the shear blades 411, 412, previously referred to in connection with Fig. 14 are pivotally supported on a suitable bracket shown in Fig. 15 at 467 bolted to the under side of top plate 30 by the screw-threaded pivot pin 468 provided with a suitable thumb nut 469. To hold the shear blades normally in working contact a spring washer 470 is interposed between the blades and the head of the threaded pivot pin 468. Shear blades 411, 412, are actuated in the same manner as the paraffin wrapper blades 202, 203, they being operatively connected by suitable links (not shown) to the rocked arm 471 which is pivotally connected to the lower extremity of bracket 467 on top plate 30 and at its lower extremity is provided with a suitable projection or anti-friction roller, not shown, in engagement with cam track on cam wheel 472 on driving shaft 73.

When the end folders 450, 451, have completed their work of folding flat upon the under side of the package the previously

crimped ends of the foil wrapper, the multiple stick package is completely enveloped in its foil wrapper and it remains only to apply and paste a binder thereto in order to complete the commercial multiple stick package. After the end folders 450, 451 have completed the foil wrapped package, the transport 392 is depressed in the manner previously described and it reciprocated 5 rearwardly in the direction of the foil wrapping mechanism in order to bring the feed slot 434 therein into position to engage the succeeding package. This leaves the foil wrapped package free and in position 10 immediately over the end folders 451 so that on the next forward reciprocation of the transport 392 this completed foil wrapped package will be engaged by the forward extremity of transport 392 and fed 15 forwardly over the forward extremities of guide plates 446, 447, and will be delivered to the foil wrapped package carrier which will transfer the package to the binder applying and wrapping mechanism. The foil wrapped package as it is delivered complete 20 from the foil wrapping mechanism is illustrated in Fig. 61 except that in this view it is inverted, for it will be observed that in the foil wrapping mechanism just described 25 the crimped ends of the foil wrapper are folded flat on the under side of the package and the complete foil wrapped package delivered from the foil wrapping mechanism in this position, that is to say, with the ends 30 of the flap folded flat on the under side of the package.

As the foil wrapped packages are discharged from the wrapping mechanism by the reciprocating transport 392 to a position 40 to be engaged by the carrier or pivoted arm 473 to be transferred to the binder-applying mechanism, they engage a pivoted stop indicated by the reference character 630, mounted on brackets 631, 632, on the top 45 plate 30, and are held in position as illustrated in Figs. 2 and 9 to intercept the foil wrapped package by suitable tension spring 633, this spring being secured at one end to bracket 631, or to the top plate if desired, 50 and at its other end to a crank arm on the pivoted stop 630. In the normal operation of the foil wrapping mechanism the wrapped packages being discharged singly from the transport, they will lodge against stop 630, 55 there to be received by the pivoted arm or carrier 473 for transferring to the binder-applying and pasting mechanism. Should, however, the carrier for any reason fail to transfer the foil wrapped packages properly 60 so that a second wrapped package should be discharged from the transport 392 before the previously discharged package has been removed, the packages will not clog the machine because the pivoted stop 630 will be rocked against the action of spring 65

633 and the excess package or packages escape.

The foil wrapped package carrier and its manner of operation will now be described. (See Figs. 2, 7, 16, and 63 to 68 inclusive, 70 and Fig. 74). This carrier or transport consists of a pivoted arm 473, provided with a suitable lug portion which is journaled on short shaft 474, which shaft is rotatably mounted in bearings as indicated at 475, 476, 75 secured to top plate 30 and is adapted to be driven by pinion 477 secured thereto and which engages with toothed rack bar 478 mounted to reciprocate vertically through top plate 30 in a suitable bearing as indicated at 479 and being provided at its lower extremity with a branch as indicated at 480, which branch and the rack bar 478 are adapted to reciprocate on opposite sides of driving shaft 74 thereby providing a bearing for the lower end of the rack bar, a suitable anti-friction roller as indicated at 481 being mounted on branch 480 in engagement with cam track 483 on cam wheel 482 which is carried and rotated by driving shaft 74. 80

The connection between the operating shaft 474 and the arm 473 is not positive, the arm 473 being preferably loosely journaled on the shaft but normally secured against rotation in relation thereto by a plunger as indicated at 484 on the interior of the arm being held in engagement with a flattened portion on the surface of shaft 474 by the action of compression spring 485. This connection between arm 473 and its actuating shaft 474 90 is sufficiently positive to normally operate the arm but should the arm meet with any unusual resistance due to an accumulation of gum, for example, at either extremity of its movement, the plunger 484 will be 100 caused to compress the spring 485 and permit the shaft 474 to rotate within the hub of the arm 473 while the arm itself would remain stationary. At the outer extremity of arm 473 preferably formed integral therewith is a fixed finger, as indicated at 473a. Between this hooked portion and the casing for the compression spring 485, a depression is formed consisting of a downwardly extending offset into which a plunger 486 is journaled. This plunger 486 carries a movable finger 487 adapted to cooperate with the fixed outer finger 473a, between which the ends of the foil wrapped package are adapted to be grasped as they 110 are discharged from the foil wrapping mechanism, since these parts lie normally in the plane of the top plate 30 and in the path of the foil wrapped packages as they come from the foil wrapping mechanism 120 (see Fig. 63). The plunger 486 is normally actuated to the position shown in Fig. 66 by a compression spring 488 on the plunger interposed between the wall of the depression in the arm 473 and the finger 487 se- 130

cured to the plunger. The outer extremity of plunger 486 is beveled (see Figs. 66 and 68) and is adapted to coöperate with the beveled outer extremity of a pin 489 extending at right angles thereto and secured to the forward extremity of the foil wrapper transport 392. The operation of this foil wrapped package carrier or transport is as follows: The rack 478 is caused to reciprocate through its connections with cam wheel 482 and through pinion 477 and shaft 474, the arm 473 carrying the fingers 473^a, 487, is moved to the position of the carrier shown in Figs. 2, 66, and other views, immediately in the path of the foil wrapped packages as they are fed from the foil wrapping mechanism by the reciprocating transport 392. As the reciprocating transport 392 reaches the forward position the beveled pin 489 is brought into contact with the beveled end of plunger 486 which is operated against the action of spring 488 to separate the finger 487 from the fixed finger on the carrier, thus permitting the foil wrapped package to be placed in position in the carrier. When the transport 392 is depressed, the beveled pin 489 will pass below the beveled surface at the forward end of the plunger 486 which will permit the movable finger 487 under the action of compression spring 488 to close upon the package and firmly clamp it between the fingers on the carrier. The carrier or transport is then operated by means of rack bar 478 and its connections through an arc of approximately 180°, thus inverting the foil wrapped package and at the end of the arc of its movement delivering the same downwardly to the binder applying mechanism (see Figs. 65 and 74).

40 The construction and mode of operation of the binder applying and pasting mechanism will now be described. The foil wrapped packages are delivered (see Figs. 2, 3, 5, 7, 10, 16, 65, and 69 to 84 inclusive).

45 The binder applying and pasting mechanism is mounted on top of plate 30 and under supporting structure 31 within convenient reach of the foil wrapped package transport or carrier 473 and comprises not only the binder wrapping and pasting mechanism but a magazine for containing a quantity of cut binders and means for feeding single cut binders from the magazine to the binder applying and pasting mechanism, the cut binder magazine itself comprising the channeled uprights 490, 491, which are secured with their channeled portions facing each other to form a chute open at the bottom for the reception of a quantity of the cut binders 13, on top plate 30. The cut binders 13 are supported at the bottom of the binder magazine by the binder feed roll 493, which is rotatably carried on shaft 494 supported on suitable bearing blocks above top plate 30 as indicated at 495, 496. Binder feed roll 493 is preferably covered on its peripheral surface with rubber or other suitable material adapted to engage and feed forwardly to the cut binder applying and pasting mechanism, 70 the cut binders from the under side of the magazine. Situated also at the bottom of the cut binder magazine and adapted to engage the lowermost binders in the binder magazine is an arm 497, being provided at 75 one end with an elongated slot, being secured to the top plate 30 by a machine screw as indicated at 498. The forward extremity of the arm 497 is a shank 499 carrying a needle 500 being provided at its upper extremity with a point adapted to pierce the lowermost binders within the cut binder magazine. The purpose of this needle 500 is to retain the lowermost cut binders in the column in position when the lowermost cut 80 binder has been fed forwardly by feed roller 493. The feed roller 493 may be provided with one or more peripheral grooves, as illustrated in the drawings, these providing a plurality of separated engaging surfaces to expedite the feeding of the cut binders forwardly from the under side of the cut binder magazine where they are engaged between the supplementary cut binder feed rolls to be presently described. Shaft 90 494 carrying cut binder feed roll 493 is rotated to feed the lowermost cut binders forwardly from the under side of the cut binder magazine to the supplemental feed rolls through which the cut binders pass to the 100 cut binder folding and pasting mechanism by an intermittently operating mechanism comprising ratchet wheel 501, gear wheel 502 loosely mounted on shaft 494 to which is secured an arm 503 carrying a pawl 504 105 in engagement with the teeth on the periphery of ratchet wheel 501 and being held normally in engagement therewith under the tension of spring 505, one end of which is secured to a suitable pin on pawl 504 and 110 the other end to a pin on arm 503. Gear 502 is adapted to rotate only a portion of its circumference in operating arm 503 and pawl carried thereby, and consequently it is necessary that it only be provided with teeth for a portion of its circumference as indicated in Figs. 72 and 73, which toothed portion is engaged by the toothed segment 506 keyed to shaft 507, which is journaled in members 495, 496, on 115 top plate 30, the shaft 507 being provided with an arm 508 by which it is adapted to be rocked through link 509, which is pivotally connected at its forward extremity at 510 to the reciprocating slide which discharges the package from the binder folding mechanism. By this construction the operation of the package discharge slide will, through the link 509 and arm 508 to which it is pivotally connected, rock shaft 120 130

507 and segment 506 carried thereby, which will in turn rotate gear wheel 502 carrying arm and spring pressed pawl 505 in engagement with teeth on ratchet 501, and rotate 5 shaft 494 and binder feed roll 493. The cut binder feed roll 493 will thus be operated at the desired intervals to feed the lowermost cut binder from the cut binder magazine by reason of its frictional contact with 10 the lowermost binder and at the same time the needle 500 engaging the lowermost cut binders in the magazine will retain in position the lowermost cut binders but the last or lowermost one, which cut binder will 15 be torn from the needle leaving a short slit in the rearmost edge as the binder is torn from the needle. The cut binder feed roll 493 therefore feeds the cut binders successively to a position where they are engaged 20 between the supplementary feed rolls carried on shafts 511, 512.

The supplemental feed rolls are indicated by the reference characters 513, 514, roll 513 being removably and flexibly mounted on 25 the rotating shaft 511 by reason of the following construction. A pin 515 (see Fig. 83) is secured in shaft 511 and co-operates with a bayonet joint as indicated at 516 in removable sleeve 517, which fits closely over 30 shaft 511. Secured to sleeve 517 is a collar 518 provided with two pins or projections 519, 520, which co-operate with suitable elongated slots in roll 513 (shown, but not designated by reference character, in Fig. 83). 35 This construction allows feed roll 513 to have a flexible or rocking movement in relation to sleeve 517 and driving shaft 511 but at the same time being positively driven through the connections therewith as described. Shaft 511 is positively driven (see 40 Figs. 2, 5 and 7) by means of gear 521 on the end thereof in mesh with a suitable gear shown in dotted lines in Fig. 5 at 522 as secured to fixed shaft 512 carrying fixed 45 lower supplementary feed roll 514 which is positively driven through sprocket wheel 523 secured to shaft 512 and sprocket chain as indicated by reference character 524 (Fig. 2) which sprocket chain passes over 50 a sprocket 525 on shaft 72 which projects through the adjacent side of the under structure 31 of the main frame (see Figs. 7 and 14). Sprocket chain 524 also drives the cut binder paste-applying rolls which will presently be described. A suitable chain tightener for this sprocket chain is provided and comprises the pivoted arm 526 pivoted on under structure 31 of the main frame and carrying at its outer extremity a suitable 55 grooved roller 527 (see Figs. 2 and 7). Supplementary binder feed roll 513 is not only movably mounted in relation to fixed supplementary feed roll 514 through its flexible connections with its driving shaft 511, 60 as described, but an adjustment is provided

by which rolls 513 and 514 may be caused to engage cut binders to pass therebetween with any desired degree of pressure and such adjustment consists in the eccentric bearing 528 shown in section in Fig. 83, the 70 same being journaled in the supporting member 496 on top plate 30 which also forms a bearing for shaft 512 carrying lower roll 514.

Eccentric bearing 528 is controlled by an 75 arm 529 (see Figs. 5 and 83) which carries an adjustable screw-threaded pin 530, the lower end of which normally contacts with the upper surface of supporting member 496, the arm 529 being normally held under 80 elastic tension by spring 531 interposed between the same and a suitable support affixed to the top plate 30. When therefore the screw-threaded pin 530 is adjusted the arm 529 will be rotated under control of 85 tension spring 531 which will rock the eccentric to move shaft 511 and roll 513 carried thereby in relation to stationary roll 514, and should there be an accumulation 90 of cut binders between the rolls, or should the roll 513 require cleaning, it may readily be removed by means of connections with operating shaft 511 as described. Lower roll 514 may be provided with a plurality 95 of peripheral raised portions which serve as 100 engaging portions for the cut binders to facilitate the feeding of the cut binders between the supplemental feed rolls. By the construction described, it will be seen that the supplemental feed rolls are constantly 105 operated when the machine is in motion, although the cut binder feed roll 493 operates only at intervals under the control of the reciprocating discharge slide 582, by which it is actuated as described. Just forwardly of the supplemental feed rolls 511, 512, is a guide preferably supported by bracket 492, as shown, this guide being indicated by the reference character 532, Fig. 10, and through the same the cut binders are 110 fed to the binder folding mechanism proper, to which the foil wrapped package transport or carrier 473 has already been described as conveying the foil wrapped package and delivering the same thereto with 115 the folded ends of the foil wrapper on the upper side of the package, the foil wrapped package having been inverted during the progress of its delivery from the foil wrapping mechanism to the binder applying 120 mechanism. Adjacent the forward end of guide 532 which guides the cut binders in their delivery from the supplemental binder feed rolls to the binder folding mechanism, the top plate 30 is cut away to permit the 125 extension of the foil wrapped package receiving mechanism which receives and retains the foil wrapped package delivered to it from carrier 473 (see Figs. 2, 16 and 74). The package receiving and retaining mech- 130

anism comprises a vertically movable support, as indicated by the reference character 533, the same being at its upper extremity approximately in width the same as the 5 length of the foil wrapped package and being cut away between the sides thereof, thus providing the two upwardly extending supports at 534 and 535 which serve to support the foil wrapped package near the ends 10 thereof. The member 533 is provided with a downwardly extending portion to which is pivotally connected parallel links 536, 537, both of which links have pivotal connection at their opposite extremities with 15 under structure 31, as indicated at 538 and 539 (see Figs. 5, 7, 10, 16, 69 and 74). This parallel link connection of the vertically moving member 533 permits the same to have movement in vertical planes under control 20 of tension spring 540, one end of which is secured to link 537 and the other to top plate 30. Driving shaft 74 in the under structure 31 carries a cam wheel 541, provided with a cam track engaging an anti-friction roller or other means for driving 25 the downwardly extending member 542 which may be branched to furnish a sliding contact on shaft 74 as a means of support and which carries at its upper extremity 30 reciprocating member 543 which is supported to reciprocate adjacent the under side of top plate 30 by entering a recess in member 544 which is secured to the under side of top plate 30. Secured to vertically moving member 35 543 at an angle thereto and extending beneath the binder wrapping mechanism is the horizontal arm 545 to which is pivotally connected at 546, 547, the spaced upright gripper jaws 548, 549. These package gripper 40 jaws 548, 549, are connected by a tension spring 550, which normally draws them together and causes their opposing inner cam surfaces to contact with suitable projections or anti-friction rollers as indicated at 551, 45 552, carried on the vertically moving member 533. The upright gripper jaw 548, being the one next to the foil wrapped package-carrier or transport, is preferably provided with an inward integral extension as indicated 50 at 553, and above this extension the material in the gripper jaw 548 is cut at an angle in order to permit the carrier or transport 473 to force the package downwardly into the binder applying mechanism, which 55 downward movement of the foil wrapped package 12 will crowd the package between the upper ends of the gripper jaws 548, 549 and cause them to be separated against the tension of spring 550 enabling the foil wrapped package 12 to press the package 60 downwardly into the binder applying mechanism on the top of the spaced branches 534, 535, on the vertically movable support 533. As soon as the foil wrapped package is 65 pressed downwardly into the position on top of spaced supports 534, 535, as illustrated in Fig. 74, the action of tension spring 550 will cause the gripper jaws to close over the ends of the foil wrapped package. Previously, however, to the introduction of the 70 foil wrapped package between the gripper jaws 548, 549, a cut binder 13 has been fed forwardly by the supplemental feed rolls 511 and 512 and mucilage roll 573 to the position illustrated in Fig. 76 in order that the downward movement of the foil wrapped package 75 into the package receiving and binder applying mechanism may force the cut binder 13 at the same time downwardly with the package and fold the sides of the binder to 80 the vertical position as illustrated in Fig. 77. The mucilage applying roll 573 engages the forward edge of the cut binder applying adhesive thereto and moving the binder until the forward edge is in engagement with the 85 bottom of the slot 561^a in the stop 561 which is adjustable in relation to the folding mechanism (see Figs. 10 and 76). This stop plate 561 will also serve to straighten a 90 binder fed angularly to the binder applying mechanism. The gripper jaw 549 is constructed differently at its upper extremity from the gripper jaw 548, although it is provided with a portion as indicated at 554 extending inwardly over the top of the foil 95 wrapped package. This extension 554, like the extension or projection 553, may be integral with the jaw 549 and constructed so that it lies directly upon the top of the foil wrapped package at the end opposite the 100 extension 553 to force the same downwardly against the spring controlled support 533. The preferred construction, however, is that illustrated in the drawings and shown in 105 Figs. 74 and 84, there being an extension 555 at the lower extremity of the projecting portion 554 pivotally connected therewith at 556 and is controlled by a movable plunger 557 extending upwardly and in contact with the lower extremity of a compression spring 110 558 contained in a suitable housing at the upper extremity of the jaw 549, the upper end of the spring being adjustably controlled by a threaded plug 559. This construction 115 has been found advantageous on account of variations that may occur between the thicknesses at the different ends of the foil wrapped packages, for when such construction is not provided and the ends of the package are not of uniform thickness, only one 120 end of the package may be gripped between the gripper jaws and the vertically movable supports 534 and 535 which will permit one end of the package to be shifted during the 125 operation of applying and pasting the binder and produce a poorly wrapped package.

The mechanism comprising the cut binder folding box consists of the lower member of the guide 532 indicated by the reference 130

character 560 which is located at the rear side of the binder folding box. The opposite side of the binder folding box consists in part of a plate 561 secured at the rear of frame 562 which carries the gumming mechanism comprising a receptacle as indicated at 563, for containing a suitable mixture of mucilage or gum as commonly used for securing binders in position around packages.

5 The frame 562, which carries the adhesive applying mechanism as well as the forward stationary binder stop plate 561, is detachably secured to a bracket 564 bolted to top plate 30. It is desirable that this entire 10 adhesive applying mechanism shall be removable from the machine for the purpose of cleaning. Bracket 564 carries stationary pin 565 adapted to engage holes in suitable lugs at the forward side of the gumming 15 mechanism frame 562 and it is preferred that one of such lugs be provided with a thumb screw as indicated at 566 (Fig. 2) by which the gumming mechanism may be secured in position on the machine. The 20 bracket 564 carries near its forward extremity some distance above the top plate 30 a short shaft to which is secured a sprocket 567 which is adapted to be engaged by sprocket chain 524 which also passes over 25 and operates sprocket wheel 523 for driving the cut binder supplementary feed rolls as described, the said short shaft being indicated by the reference character 568 (Fig. 5). The shaft 568 carries a gear 569 which 30 meshes with gear 570 rotatably supported on bracket 564, the short shaft supporting the gear 570 being indicated by the reference character 571. The shafts 568 and 571 are for the purpose of driving the adhesive applying 35 mechanism consisting of the three distributing rolls or cylinders as indicated by the reference characters 572, 573, 574, all of which are rotatably carried in the detachable frame 562 on short shafts which project 40 only a short distance beyond the outer end of frame 562 and are provided with some suitable form of bayonet joint as shown, or clutch adapted to engage the co-operating adjacent ends of driving shaft 45 568 which engages distributing roll 574 and shaft 571 which engages roll 572. The roll 573 is also positively driven by a short shaft 575 carrying pinion 576, also in engagement with gear 569. Roll 572 is of plain cylindrical 50 form as shown and is mounted to rotate within the gun receptacle 563 while distributing rolls 573 and 574 are provided with a plurality of narrow peripheral flanges adapted to contact with each other 55 and the flanges on roll 574 being adapted to engage the cylindrical surface of distributing roll 572. The roll 572 being contained wholly within the adhesive receptacle 563, as it is rotated, will carry on its 60 surface a quantity of the liquid mucilage or adhesive which will be taken therefrom by the peripheral flanges on the roll 574, which roll being in contact with roll 573 will transmit a portion of the mucilage or adhesive to the flanges thereon and these flanges extending downwardly close to the top surface of binder stop plate 561 will, at the instant that the cut binder is fed forwardly over the binder wrapping box, engage the forward upper edge of the cut binder and apply the adhesive or mucilage thereto in a plurality of places along the forward upper edge thereof where the peripheral flanges come in contact with the binder. For the purpose of preventing the 70 distributing roll 572 from imparting an undue quantity of the adhesive or mucilage to the distributing and applying rolls 574, 573, a suitable scraper 577 is provided having a sharp edge engaging the surface of roll 572 and being secured at the bottom of receptacle 563 by the uprights 578, 579, and being adjustable in relation to the roll 572 by suitable thumb screws 580, 581, carried by the uprights 578, 579, and at their forward extremities engaging the scraper 577. By this adjustment of the scraper 577 the quantity of gum or mucilage to be carried up by the distributing roll 572 may be accurately determined.

75 As already set forth in the detail description of the construction of this adhesive applying mechanism, the frame 562 and all the mechanism carried thereby may be readily removed from the machine simply by loosening the thumb screw 566, since the shafts driving the distributing and applying rolls are dividing as described. This is an important feature of the invention because of the nature of the mucilage or other adhesive material used in securing the cut binders around the packages since such substances have a tendency to dry out and otherwise become difficult to work, particularly under certain atmospheric conditions, and consequently these parts require frequent cleansing, which often requires considerable time, as they must be thoroughly soaked in water or some other suitable liquid in order to be cleansed, and when constructed as described they may be removed whenever the machine is not in operation during which time they may be conveniently immersed or soaked in a cleansing bath.

80 When the cut binders 13 are fed over the binder folding box by the supplemental feed rolls 513, 514, (see Fig. 76) the forward edge of the binder is engaged between the adhesive applying roll 573 and the adjustable plate 561. This plate is provided with a groove as indicated at 561^a which acts as a stop for the forward edge of the binder and also serves to right or position the binder should its forward edge not be fed forwardly exactly parallel with the axis of the 85 90 95 100 105 110 115 120 125 130

feed and mucilage applying rolls. This is an important feature in properly positioning the cut binders over the binder wrapping mechanism. At the time adhesive is applied to the binder as described the vertically movable support 534 is in its elevated position flush with the tops of the guide plates 560, and 561, which also serve to partially fold or begin the folding operation 5 by somewhat deflecting the sides of the binder as it is pressed downwardly into the folding mechanism. When the binder is 10 immediately over the folding mechanism the package carrier or transport 473 conveys the foil wrapped package to the binder applying mechanism and places the same in the position illustrated in Fig. 76 immediately 15 on the top of the vertically movable support 534 and causing the foil wrapped package to engage the upper surface of the binder. The carrier or transport 473 then moves farther down to the position illustrated in Fig. 77, causing the vertical side flaps of the binder 13 to be folded to the vertical 20 position. This downward movement of the package is continued much farther than illustrated in Fig. 77 or until the package reaches the extreme lowermost position of its movement. However, when the package reaches about the relative position in relation 25 to the folders as indicated in Fig. 77, it has passed below the projection 553 on gripping jaw 548 and below the pivoted elastically controlled member 555 on gripping jaw 549. The carrier or transport 30 473 is then withdrawn and the further downward movement of the gripper jaws 548, 549 draw the package downwardly to the extreme lower limits of its movement 35 and at the same time the downward movement of the package, the same resting upon the members 534, 535, forces downwardly the vertically movable member 533 which being operated to its lowermost position 40 against the action of spring 540 which will operate to throw the binder folding mechanism into gear. It may be here remarked that the paraffin paper and foil wrapping mechanisms heretofore described were constantly 45 in operation whenever the machine itself was operated. With respect, however, to the binder wrapping or folding mechanism, it is an important part of the invention that the same be thrown out of operation 50 55 in connection with the remainder of the machine should the machine for any reason fail to deliver a foil wrapped package in proper position to the binder applying mechanism because if there should be a failure 55 to deliver a foil wrapped package, the binder feeding and applying mechanism if continuously operated would continue to present cut binders to the binder applying and pasting mechanism which would result in clogging and stopping the machine.

It has been heretofore observed that the cut binder feed roller 493 is operated from the reciprocating slide which discharges the packages from the binder folding mechanism, the discharge slide itself being indicated by the reference character 582 and the rocker arm carrying the same, (and to which it is pivotally connected by the pivot pin 510 to which is also connected the link 509 for operating the binder feed roll) being indicated by the reference character 583. The rocker arm 583 is pivotally secured to the under structure 31 at 584 and at its lower extremity carries an anti-friction roller 585 engaging with the cam track 586 in cam wheel 587 secured to shaft 74. Cam wheel 587 is mounted on shaft 74 but is mounted loosely thereon so that it may rotate independently of said shaft and being controlled in the following manner: Pinned to shaft 74 adjacent the hub of cam wheel 587 by pin 588 (see Figs. 16 and 70) is a collar 589 provided with a recess in the side thereof as indicated at 590 adapted to take one end of the plunger 591 which is carried in a suitable housing in the hub of cam wheel 587 and pressed normally into engagement with the adjacent face of collar 589 by compression spring 592. Secured to plunger 591 and at approximately right angles thereto is a pin 593 by which plunger 591 is adapted to be controlled to cause it to be disengaged from recess 590 in constantly rotating shaft 589 against the action of spring 592. The cam wheel 587 is provided with an eccentric portion as indicated at 587^a. This eccentric portion 587^a extends for a portion of the distance around the periphery of the cam wheel, gradually increasing its eccentricity to the point 587^a where the eccentric portion terminates abruptly. Secured to the under structure 31 is a stationary pin 594 on which is pivotally supported an arm 595 having pivotal connection with the lower end of link 596 which at its upper extremity is pivotally connected to the lower parallel link 537 supporting the vertically movable support 533, the upper branches 534, 535 of which are in engagement with the package in the binder wrapping mechanism. Secured to arm 595 is a supplemental arm 597, the upper extremity of which is beveled as indicated at 598, Fig. 70, and adapted to engage pin 593 on plunger 591. Formed integrally with arm 595 or secured thereto is a second supplemental arm 599, the forward extremity of which is adapted to be engaged by the surface of cam wheel 587 and particularly by the eccentric portion 587^a.

When there is no package of foil wrapped gum in the binder applying and wrapping mechanism, the branches 534, 535 on the vertically moving member 533 will be held at the uppermost limits of their movement

by the action of spring 540 and the anti-friction rollers 551, 552, will engage the sides of the gripper jaws 548, 549, and cause them to be separated as illustrated, for example, in Fig. 16, the gripper jaws being separated against the action of spring 550 to allow them to escape contact with the upper ends of 534, 435. During this period of operation of the machine the support 533 being at the upper limits of its movement will hold the link 537 at the upper limits of its movement, elevating, at the same time, the pivoted arm 595 through connecting link 596 and raising the beveled extremity 598 of the supplemental arm 597 to a position where it will contact with pin 593 on plunger 591 causing plunger 591 to be withdrawn against the action of compression spring 592, thus freeing the cam wheel 587 from contact with the depression 590 and collar 589, thus allowing cam wheel 587 to remain stationary while the constantly operating shaft 74 and collar 589 secured thereto are free to turn. When the support 533 therefore is allowed to remain at the upward limits of its movement, as it does when there is no foil wrapped package in the binder wrapping mechanism, the cam wheel 587 will remain stationary on shaft 74 and the rocker arm 583 carrying the movable rear binder flap folder will remain stationary as will the cut binder feed roller 493 which is operated by rocker arm 583.

The above described operation of the parts is made possible by the fact that the vertically movable package support 533 is depressed only when there is a package in the binder applying and wrapping mechanism. It will be remembered that gripper jaws 548, 549, are constantly operated by the vertical reciprocations of the constantly operating shaft 543 (see Fig. 74). But when there is no foil wrapped package engaged between the upper extensions on the gripper jaws and the branches 534, 535, the gripper jaws will move downwardly independently of the support 533 and the upper extensions 534, 535, carried thereby which movement will carry the indentations as indicated at 548^a and 549^a beyond the anti-friction rollers 551, 552, which will separate the gripper jaws 548, 549, so that they will not engage and depress the support 533 just as indicated in Fig. 16; and consequently the cam wheel 587 will remain inoperative and likewise the binder feeding and folding mechanism operated thereby until such time as a foil wrapped package shall be introduced into the binder folding mechanism. When, however, a foil wrapped package is properly introduced into the binder folding and applying mechanism it will be seen that the relative position of the parts will be as indicated in Fig. 74 wherein the downward movement of vertically moving shaft 543 will cause the gripper jaws 548, 549 to be depressed and the package being interposed between the vertical extension 534, 535, on support 533 will lower said support and at the same time depress the supplemental arm 597 so that its angular surface will fail to engage pin 593 on plunger 591, and will permit said plunger to engage its corresponding recess in driving collar 589 on constantly rotating shaft 74. The intermittently operated cam wheel 587 is provided with a second cam track as indicated at 600 (see Fig. 70) which is adapted to take an anti-friction roller 601 on the lower extremity of rocker arm 602 which is pivotally secured to the under structure of the machine by the same pivot pin 584 which supports rocker arm 583. At its upper extremity rocker arm 602 is pivotally connected with rear binder flap folder 603 by pivot pin 604. It will be noted that rear binder flap folder 603, like the reciprocating package discharge member 582, is provided with a forward extension or slide supported by a depressed portion formed on main frame 30 (see Figs. 10, 69, 76, 78, and 79). The member 582 being mounted to slide over the surface of the forward extension of folder 603, the pins 510 and 604 may be driven into members 582 and 603 and be loosely journaled in blocks as indicated at 605 carried in the slotted upper ends of both rocker arms 583 and 602. (see Fig. 73). This construction prevents bending of the parts since the rocker arms move in the arc of a circle on fixed pin 584 as a common center, while folder slide 603^a and reciprocating discharge member 582 are limited to longitudinal movement in relation to top plate 30. Over the top of the forward extension of package discharge member 582 and just forward of what may be termed the binder wrapping box is a thin plate 606 supported on top plate 30, and having two separated extensions 606^a which project through and form a portion or the bottom of the binder wrapping box, the material between said extensions being cut away so as not to interfere with the movement of branches 534, 535, rear binder flap folder 603 and discharge slide 582 (see Figs. 16, 74, 76, 78 and 79).

The foil wrapped package having been advanced through the binder applying and pasting mechanism to the position already described and as illustrated in Figs. 76 and 77, the forward upper edge of the binder having received a quantity of mucilage or adhesive and the forward and rear sides of the binder being brought to the vertical position as illustrated in Fig. 77, the downward movement of support 533 by the pressure exerted on the upright branches 534, 535, thereof will when the support 533 reaches the lowermost limits of its move- 125 129 130 135 140 145 150 155 160 165 170 175 180 ment operate the clutch mechanism described to cause the cam wheel 587 to be rotated on constantly rotating drive shaft 74. When the package carrying the binder 13 with it, as illustrated in Fig. 77, reaches the lowermost limits of its movement it will rest upon the top of the rearwardly projecting portions of the slotted plate 606 which forms the bottom of the binder wrapping box, and in front of the vertically projecting ledge on package discharge member 582 as indicated by the reference character 582^a. At this instant the package is still under control of the gripper jaws 548, 549, being held firmly between the engaging projections 553, 554, thereon and the projections 554, 555, on the support 533. Although the downward movement of the support 533 operates to release the plunger 591 the cam wheel 587 will yet remain stationary for a short time or until the plunger reaches the forward extremity of the recess 590 on collar 589. During this interval the package will continue its downward movement until it reaches the lowermost limit on top of discharge member 582 in front of vertical projection 582^a. The first movement of cam wheel 587 when thrown into gear is to give the package discharge member 582 a slight forward movement while the package is still held by the gripper jaws 548, 549. This tends to shape the rear side of the package after which the discharge member 582 remains stationary while the rear binder flap folder 603 is advanced to the position illustrated in Fig. 78 folding down flat upon the top of the package the rear flap of the binder. The reciprocating member 543 has now reached the lowermost limits of its movement and started to move upwardly, releasing the gripper jaws 548, 549, from the top of the package. At the same time the upward movement of the gripper jaws 548, 549 causes the anti-friction rollers 551, 552 on support 533 to ride below the depressions 548^a, 549^a, separating the gripper jaws, making it possible for the rear binder flap folder to fold the rear flap over the top of the package without interference. The reciprocating discharge member 582 is now operated to the forward limit of its movement as indicated by the relative position of the parts in Fig. 79 carrying the package out of the binder folding box onto the top of plate 606 and under forward flap folder consisting of rollers 607, 608, supported by suitable frames 609, pivotally mounted on a pin 610 carried by block 611, which is secured to shaft 612 slidably supported in lugs 613, 614, on bracket 564. Interposed between block 611 carrying pin 610 and lug 613 is the compression spring 615 adapted to hold rollers 607, 608 normally adjacent the binder folding box. However, should for any reason

a number of packages of gum become wedged in the folding box, the folding rollers 607, 608, and their supports will move out of the way against the compression of spring 615. Elastic downward pressure is given to rollers 607, 608, by means of coil springs 616, 617, secured at one end to the supporting pin 610 and at their other ends to frame members 609. As the discharge member 582 moves the package out of the folding box to the position shown in Fig. 79, the rollers 607, 608, will press the forward and gummed flap of the binder flat down upon the upper side of the package, which operation completes the wrapping of the package. The reciprocating discharge member 582 and the rear binder flap folder 603 are now returned to their normal position ready to receive an incoming foil wrapped package and the reciprocating shaft 543 carries the gripper jaws 548, 549, farther upwardly ready to receive another incoming package.

ceive another incoming package.

Before the wrapped package is discharged from the binder wrapping mechanism, the supplemental arm or ledge 599 secured to pivoted arm 95 rides on the eccentric portion 587^a of cam 587 which holds the support 533 at the lowermost limits of its movement until the cam 587 is rotated beyond the extremity 587^b of the eccentric portion 587^a. When the package has been discharged under the forward flap folding rollers 607, 608 as described and when the package discharge member 582 and the rear binder flap folder 603 have been returned to their initial position at the rear of the binder folding box as illustrated, for example, in Fig. 76, the supplemental arm 599 controlling arm 595 rides off the eccentric portion 587^a of cam 587 and the support 533 under the action of spring 540 returns to the upward limit of its movement, thus placing all the parts ready to receive another incoming foil wrapped package and the cut binder to be applied to the same. When the arm 595 is released to permit the upward movement of the package support 533, it will carry the beveled end 598 of arm 597 to a position where pin 593 on plunger 591 will be engaged and operated against the action of spring 592 to disengage the cam 587 from the constantly rotating sleeve 589, which will permit the cam 587 and the folding and discharging mechanism as well as the cut binder feed mechanism to remain at rest until again thrown into operation in the manner previously described by the introduction of another foil wrapped package into the binder applying and wrapping mechanism. It should be observed, however, that each forward reciprocation of the package discharge member 582 operates the cut binder feed mechanism to position a cut binder for the subsequent package to

which the binder is to be applied. The completely wrapped package, after being passed under the forward binder flap folding roller 607, 608 remains in that position under the spring pressure of these rollers on the top of the forward edge of plate 606 while the package discharge member 582 is reciprocated back to its original position below the binder folding box when the operation just described of applying the binder to a foil wrapped package is repeated with respect to the next package delivered to the binder folding and applying mechanism. The completely wrapped package is therefore allowed to remain under the spring pressure of rollers 607, 608, for a brief interval which will allow the adhesive substance to set and retain the binder around the package. The next completely wrapped package will crowd the package forwardly a distance equal to the width of the package over the plate 606 and this operation will be repeated, the wrapped packages being crowded to the forward side of the machine, passing off plate 606 and onto top plate 30 (see Figs. 80 and 81). A completely wrapped package with the binder applied is illustrated in Fig. 82. Pivotally secured to the frames 609 supporting the forward flap folding rollers 607, 608, are flexible metallic strips 618, 619, which are preferably of about the same width as the length of rollers 607, 608, and extend toward the front of the machine over a portion of top plate 30, being adapted to lie over the top of the completely wrapped packages as illustrated, their extremities being provided with suitable weights as indicated at 620, 621, by which they are held over the top of the stream or row of completely wrapped packages to prevent the same from buckling and to cause the packages to be guided along top plate 30 to the converging guides 622, 623, which are secured to the front edge of the top plate 30. Projecting forwardly over the edge of top plate 30 between the guides 622, 623, is a thin plate as indicated at 624 which provides a narrow extension along which the completed packages are allowed to pass from between guides 622, 623, for the purpose of expediting the placing of the completely wrapped packages in suitable packing boxes. The strip 624 may be of any desired length to accommodate the same to the length of the packing boxes in which the completely wrapped packages are to be placed. The packing box is slipped over the end of the member 624 as indicated by the reference character 625 in Figs. 80 and 81, and the operator counting the required number of packages to fill the box may place one hand on the rearmost package of the number and grasping the box 625 in the other hand may crowd the required number of packages to fill the box off the strip 624

and at the same time allow the box to follow the packages as they pass off the end of the strip, which will enable the packages to be deposited in the box with much less effort and greater speed than where it is required that each package be counted and handled separately. 70

In order that the invention might be fully understood the details of the preferred embodiment have been specifically described, 75 but it will be apparent that many modifications and changes may be made by those skilled in the art without departing from the purpose and spirit of the invention, and

What we claim is:

1. The combination in a machine having wrapping mechanism, of a magazine for containing articles to be wrapped, means for delivering articles from the magazine to the wrapping mechanism, said means being adapted at each operation thereof to remove articles in predetermined quantities from the lower extremity of said magazine, and means for correctly positioning the lowermost articles within the magazine for engagement by said delivering means comprising a spring controlled pivoted member held normally out of the path of the articles within the magazine, and means for operating said pivoted member into the path of the articles within the magazine against the tension of the said controlling spring. 90

2. The combination in a machine having wrapping mechanism, of a magazine for containing articles to be wrapped, means 100 for delivering articles from the magazine to the wrapping mechanism comprising a reciprocating member co-operating with the said magazine, said reciprocating member being adapted at each operation thereof to remove articles to be wrapped in predetermined quantities from the lower extremity of said magazine, and means for positively positioning the lowermost articles in the magazine for engagement by said reciprocating member comprising a pivoted member secured adjacent the bottom of the magazine, the said pivoted member being spring-controlled and operated into the path of the articles at the lower extremity 110 of the magazine by the said reciprocating member. 115

3. The combination in a machine having wrapping mechanism, of a magazine for containing articles to be wrapped, means 120 for delivering articles from the magazine to the wrapping mechanism, said means being adapted at each operation thereof to remove articles to be wrapped in predetermined quantities from the lower extremity of said magazine and comprising a slotted reciprocating member, means for correctly positioning the lowermost articles in the magazine for engagement by the said slotted reciprocating member, said means 125

comprising a pivoted member adapted to be held normally out of the path of the articles within the magazine, and means on the slotted reciprocating member for operating 5 the said pivoted member into the path of the articles within the magazine.

4. The combination in a machine having wrapping mechanism, of a magazine for containing articles to be wrapped, means 10 for delivering articles from the magazine to the wrapping mechanism, said means being adapted at each operation thereof to remove articles to be wrapped from the lower extremity of said magazine and comprising 15 a plunger reciprocating at an angle to the path of movement of articles through the magazine and being provided with a feed slot adapted to receive articles in predetermined quantities from the magazine, 20 means for correctly positioning the lowermost articles in the magazine for engagement by said delivering means, and means carried by the said delivering means for correctly positioning the articles and retaining 25 them in position while carried by said delivering means.

5. The combination in a machine having wrapping mechanism, of a magazine for containing articles to be wrapped, means 30 for delivering articles from the magazine to the wrapping mechanism, said means comprising a plurality of longitudinally moving arms adjacent the open end of the magazine and being provided with slots 35 adapted to engage a predetermined number of articles from the magazine at each reciprocation thereof, means for positively positioning the lowermost articles in the magazine for engagement by the slots in 40 said longitudinally moving arms, the said means comprising members pivotally connected to the magazine and operated by the said longitudinally moving arms.

6. The combination in a machine having 45 wrapping mechanism, of a magazine for containing articles to be wrapped, means for delivering articles from the magazine to the wrapping mechanism comprising a plurality of longitudinally-moving arms, elastically controlled pivoted members adjacent the lower extremity of the magazine adapted 50 to position the lowermost articles of the magazine for engagement by said longitudinally-moving arms, means for operating said pivoted members from said longitudinally-moving arms, and means carried by 55 said longitudinally-moving arms for positioning the articles while being carried thereby.

7. The combination in a machine having 60 wrapping mechanism, of a magazine for containing sticks of gum to be wrapped, means for delivering the sticks of gum from the magazine to the wrapping mechanism comprising a plurality of spaced longitudi-

nally-moving arms provided with feed slots, means for correctly positioning the lowermost articles within the magazine for engagement by the said feed slots, said means being secured to the magazine and operated by the said longitudinally-moving arms, and means carried by the said arms for positioning sticks of gum longitudinally of the said feed slots during the operation of delivering sticks of gum from the magazine to the wrapping mechanism. 70 75

8. The combination in a machine having wrapping mechanism, of a magazine for containing articles to be wrapped, means for delivering articles from the magazine to 80 the wrapping mechanism, said means being adapted at each operation thereof to remove articles to be wrapped from the lower extremity of said magazine and comprising a movable member carrying a plurality of 85 longitudinal arms being provided with feed slots, means carried by the said arms adapted to position articles from the magazine longitudinally of the said feed slots, said means comprising a pair of arms pivoted to 90 the longitudinally-moving arms and being provided at their forward extremities with means for engaging the ends of the article within the feed slots, elastic means for holding said pivoted arms normally in engagement with articles carried by said feed slots, and means operable from the machine for opening the said pivoted arms against the action of said elastic means. 95

9. The combination in a machine having 100 wrapping mechanism, of a magazine for containing articles to be wrapped, means for delivering articles from the magazine to the wrapping mechanism, said means being adapted at each operation thereof to remove 105 a single article from the lower extremity of said magazine and comprising a pair of reciprocating arms provided with feed slots, means carried by the magazine and operated by the said reciprocating arms for correctly 110 positioning the lowermost articles in the magazine for engagement by the said feed slots in the reciprocating arms, means carried by the reciprocating arms for positioning the article longitudinally of the slots 115 therein after leaving the magazine, and means for receiving the article and delivering the same to the wrapping mechanism comprising vertically-moving picks.

10. The combination in a machine having 120 wrapping mechanism, of a magazine for containing articles to be wrapped, means for delivering articles from the magazine to the wrapping mechanism, said means being adapted at each operation thereof to remove 125 articles to be wrapped in predetermined quantities from the lower extremity of said magazine, and means for correctly positioning the lowermost articles in the magazine for engagement by said delivering means 130

- comprising a plurality of eccentrically pivoted members at the lower extremity of the magazine, normally held under spring tension out of the path of articles within the magazine, and means for operating the said eccentrically pivoted members into the path of the articles within the magazine. 11. The combination in a machine having wrapping mechanism, of a magazine for containing articles to be wrapped, means for delivering articles from the magazine to the wrapping mechanism, said means being adapted at each operation thereof to remove a single article to be wrapped from the lower extremity of said magazine, means for receiving the articles from the delivering means and introducing them into the wrapping mechanism on top of a wrapper previously positioned over the wrapping mechanism, a vertically-moving member adapted to coöperate with the means for introducing the article and the wrapper to the wrapping mechanism, means for folding the longitudinal sides of the wrapper to the vertical position by the introduction of the article into the wrapping mechanism, a movable folder for folding the rear side flap, a stationary plate forming the forward side of the folding mechanism and under which the article is adapted to be passed to fold the forward said flap, a reciprocating transport for feeding the article under the said plate, and means adjacent the said plate by which the ends of the wrapper are folded flat upon the package during the passage of the article and wrapper under the plate. 12. The combination in a machine having wrapping mechanism, of a magazine for containing articles to be wrapped, a support for a strip of wrapping material, means for feeding the strip of wrapping material from the support to the wrapping mechanism comprising a movable plate, a plurality of independently movable spring-controlled nipper-jaws coöoperating with said plate, and cutters adjacent the wrapping mechanism for severing the wrappers from the strip. 13. The combination in a machine having wrapping mechanism, of a magazine for containing articles to be wrapped, means for delivering articles from the magazine to the wrapping mechanism, a support for a strip of wrapping material, and means for feeding the wrapping material to the wrapping mechanism, said means comprising a movable plate, and a plurality of independently movable elastically-controlled nipper-jaws coöoperating with said plate. 14. The combination in a machine having wrapping mechanism, of means for feeding articles to be wrapped, a support for a strip of wrapping material, and means for feeding the strip of wrapping material to the wrapping mechanism comprising a recipro- 5 10 15 20 25 30 35 40 45 50 55 60 65 70 75 80 85 90 95 100 105 110 115 120 125 130
- cating plate, a plurality of independently movable pivoted nipper-jaws coöoperating with said plate, and means for operating in unison said nipper-jaws to seize and to release the strip of wrapping material. 15. The combination in a machine having wrapping mechanism, of means for delivering articles to be wrapped to the wrapping mechanism, a support for a strip of wrapping material, means for feeding the free end of the strip of wrapping material to the wrapping mechanism comprising a reciprocating plate, a plurality of independently movable nipper-jaws coöoperating with said plate, means for operating said nipper-jaws to seize the free end of the strip, means for operating the said reciprocating plate, means for opening the said nipper-jaws to release the free end of the strip, and means for severing a wrapper from the strip. 16. The combination in a machine having wrapping mechanism, of a magazine for containing articles to be wrapped, means for delivering articles from the magazine to the wrapping mechanism, a support for a strip of wrapping material, means for feeding the free end of the strip to the wrapping mechanism comprising a reciprocating plate, a plurality of independently movable nipper-jaws pivotally secured to said plate, means for operating the nipper-jaws to close them upon the free end of the strip, means for moving the reciprocating plate carrying said nipper-jaws, means for severing the wrapper from the free end of the strip, and means for opening the nippers to release the cut wrapper. 17. The combination in a machine having wrapping mechanism, of a magazine for containing articles to be wrapped, means for delivering articles from the magazine to the wrapping mechanism, a support for a strip of wrapping material, a reciprocating plate, a plurality of nipper-jaws secured to and coöperating with said plate to grasp the free end of the strip and draw the same over the wrapping mechanism, means for closing the nipper-jaws on the wrapping material, means for severing the wrapper from the strip, a plunger adapted to force the article into the wrapping mechanism on top of the wrapper, means for operating said plunger, and means operated by said plunger-operating means for opening the nipper-jaws to release the wrapper. 18. The combination in a machine having wrapping mechanism, of a magazine for containing articles to be wrapped, means for delivering articles from the magazine to a position adjacent the wrapping mechanism, means for supporting a strip of wrapping material, means for feeding the strip of wrapping material to the wrapping mechanism, means for severing a wrapper from the free end of the strip, a reciprocating 120 125 130

plunger adjacent the wrapping mechanism, picks carried by said plunger being adapted to impale the article and to force the same into the wrapping mechanism on top of the 5 wrapper, and means operated by said reciprocating plunger for releasing the wrapper-feeding means.

19. The combination in a machine having a wrapping mechanism, of means for delivering 10 articles to the wrapping mechanism to be wrapped, a support for a strip of wrapping material, means for feeding the wrapping material to the wrapping mechanism, and means for severing the wrapper from 15 the free end of the strip, said means for feeding the wrapping material comprising a movable plate carried on a standard, a plurality of nipper-jaws pivotally connected to and co-operating with said plate, a link connection 20 between said standard and said nipper-jaws for controlling the movement of said nipper-jaws, and adjustable means secured to said standard for controlling the movement of said links.

20. The combination with a magazine for containing articles to be wrapped, of wrapping mechanism for wrapping individual articles, an accumulating chamber, means for conveying individual articles from the 25 wrapping mechanism to the accumulating chamber, a second wrapping mechanism for applying a foil wrapper to a predetermined number of said individually wrapped articles, means for conveying a predetermined number of individually wrapped articles from the accumulating chamber to the said foil wrapping mechanism, means for operating the foil-wrapping mechanism, thereby producing a multiple-stick package, 30 a cut binder applying mechanism, means for transferring a multiple-stick package from the foil wrapping mechanism to the binder applying mechanism, means for operating the binder applying mechanism to apply a 35 binder to the multiple-stick package, and means for discharging a multiple stick package with the binder applied thereto from the machine.

21. The combination with a magazine for containing articles to be wrapped, of wrapping 40 mechanism for applying wrappers to individual articles, an accumulating chamber, means for conveying individual articles from the wrapping mechanism to the accumulating chamber, a foil wrapping mechanism for applying a foil wrapper to a predetermined number of said individually wrapped articles, means for operating the foil wrapper mechanism, means for conveying 45 a predetermined number of individually wrapped articles from the accumulating chamber to the foil wrapping mechanism, a binder applying and pasting mechanism, means for operating the binder applying 50 and pasting mechanism, means for conveying 55 a predetermined number of individually wrapped articles from the accumulating chamber to the foil wrapping mechanism, a binder applying and pasting mechanism, means for operating the binder applying 60 and pasting mechanism, means for conveying 65 a predetermined number of individually wrapped articles from the accumulating chamber to the foil wrapping mechanism, a binder applying and pasting mechanism, means for operating the binder applying and pasting mechanism,

ing the foil wrapped package from the foil wrapping mechanism to the binder applying and pasting mechanism, and means for discharging the completely wrapped package with the binder applied and pasted 70 thereon from the binder applying and pasting mechanism.

22. The combination with a magazine for containing articles to be wrapped, of wrapping mechanism for wrapping individual 75 articles, a second wrapping mechanism for applying a wrapper to a predetermined number of said individually wrapped articles, means for conveying a predetermined number of individually wrapped 80 articles from the first said wrapping mechanism to the second said wrapping mechanism, a binder-applying and pasting mechanism, means for operating said wrapping mechanisms and the binder applying and 85 pasting mechanism, and means for conveying the wrapped packages from the second wrapping mechanism to the binder-applying and pasting mechanism.

23. The combination with a magazine for 90 containing articles to be wrapped, of wrapping mechanism for applying wrappers to each of said individual articles, an accumulating chamber, means for conveying individually wrapped articles from the wrapping 95 mechanism to the accumulating chamber, a second wrapping mechanism for applying a wrapper to a predetermined number of said individually wrapped articles, means for conveying a predetermined number of individually wrapped 100 articles from the accumulating chamber to the last said wrapping mechanism, thereby producing a multiple-stick package, a binder-applying and pasting mechanism, means for conveying the multiple-stick package from the last wrapping mechanism to the binder-applying and pasting mechanism, and means for discharging the completely 105 wrapped package with the binder applied 110 pasted thereto from the machine.

24. The combination with wrapping mechanism for applying wrappers to individual articles, an accumulating chamber, means for conveying individually wrapped articles 115 from the wrapping mechanism to the accumulating chamber, a second wrapping mechanism for applying a wrapper to a predetermined number of individually wrapped articles, means for conveying a predetermined number of individually wrapped articles from the accumulating chamber to the last said wrapping mechanism, thereby producing a multiple-stick package, a binder applying 120 and pasting mechanism, means for conveying the multiple-stick package from the last said wrapping mechanism to the binder applying and pasting mechanism, means for operating the said wrapping mechanisms and the binder applying and pasting mechanism, 125 130

and means for discharging the completely wrapped multiple-stick packages from the binder applying and pasting mechanism.

25. The combination with wrapping mechanism adapted to apply wrappers to individual articles, of an accumulating chamber, means for transferring articles from the said wrapping mechanism to the accumulating chamber, a second wrapping mechanism for applying foil wrappers to a predetermined number of individually wrapped articles, means for transferring a predetermined number of individually wrapped articles from the accumulating chamber to the foil wrapping mechanism, a binder applying and pasting mechanism, means for transferring the wrapped packages from the foil wrapping mechanism to the binder applying mechanism, means for operating all of the said wrapping mechanisms, the said transferring mechanisms and the binder applying and pasting mechanism, and means for discharging the completely wrapped packages from the binder applying and pasting mechanism.

26. The combination with a magazine for containing articles to be wrapped, of wrapping mechanism for wrapping individual articles, an accumulating chamber, means for conveying individually wrapped articles from the wrapping mechanism to the accumulating chamber, a multiple-stick wrapping and binder applying and pasting mechanism, means for transferring individually wrapped articles in predetermined quantities from the accumulating chamber to the multiple-stick wrapping and binder applying and pasting mechanism, means for retaining the individually wrapped articles within the accumulating chamber, and means for operating the said retaining means to release the articles within the accumulating chamber when a predetermined number of said singly wrapped articles have accumulated therein.

27. The combination with wrapping mechanism for applying wrappers to individual articles, of an accumulating chamber, means for conveying individually wrapped articles from the wrapping mechanism to the accumulating chamber, a second wrapping mechanism for applying a wrapper to a predetermined number of said individually wrapped articles, and means for conveying a predetermined number of individually wrapped articles from the accumulating chamber to the last said wrapping mechanism, said means comprising a frame provided with opposing jaws, one or more of which are spring-controlled, said frame being carried on parallel links, and means for rocking the said parallel links to operate said frame, said means comprising a rotatable shaft on which one of said links is journaled, a spring-pressed plunger carried

by said link engaging a depression on said shaft, and means for rocking said shaft.

28. The combination with mechanism for applying wrappers to individual articles, an accumulating chamber, means for conveying the individually wrapped articles to the accumulating chamber, a second wrapping mechanism for applying a wrapper to a predetermined number of individually wrapped articles, means for retaining the individually wrapped articles within the accumulating chamber, means for conveying the individually wrapped articles in predetermined quantities to the last said wrapping mechanism, and means for delivering the individually wrapped articles in predetermined quantities from the accumulating chamber to said conveying means.

29. The combination with mechanism for applying wrappers to individual articles, an accumulating chamber, means for conveying individually wrapped articles to the said accumulating chamber, a second wrapping mechanism for applying wrappers around a predetermined number of individually wrapped articles, means for transferring a predetermined number of individually wrapped articles from the accumulating chamber to the last said wrapping mechanism, a vertically-moving plunger for introducing the singly wrapped articles in predetermined quantities into the last said wrapping mechanism on top of a previously cut and positioned wrapper whereby the longitudinal flaps of the wrapper are folded to a vertical position, a pivoted folder for the rear longitudinal flap, a stationary plate for folding the forward longitudinal flap, means for discharging the package beneath the last said folder to fold the said flap, means for crimping and folding the ends of the wrapper around the multiple stick package, a binder applying and pasting mechanism, means for conveying the package from the last said wrapping mechanism to the binder applying and pasting mechanism, means for operating the binder applying and pasting mechanism, and means for discharging the completed package with the binder applied and pasted thereon from the machine.

30. The combination with mechanism for applying wrappers to individual articles to be wrapped, of an accumulating chamber, means for conveying the individually wrapped articles from the wrapping mechanism to the accumulating chamber, a second wrapping mechanism for applying wrappers around a predetermined number of individually wrapped articles, means for conveying the individually wrapped articles in predetermined quantities from the said accumulating chamber to the last said wrapping mechanism, means comprising a vertically-moving plunger for introducing a

predetermined number of individually wrapped articles into the last said wrapping mechanism and folding the longitudinal side flaps of the wrappers, a reciprocating folder for folding the rear longitudinal side flap of the wrapper, a spring-pressed plate at the rear side of the folding mechanism under which the package is adapted to be passed to fold the forward side flap, a reciprocating transport for conveying the package beneath the said plate and folding the forward longitudinal flap, means for crimping and folding the ends of the wrapper around the package of individually wrapped articles, a binder applying and pasting mechanism, means for transferring the wrapped package from the last said wrapping mechanism to the binder applying and pasting mechanism, and means for discharging the completely wrapped package with the binder applied and pasted thereon from the machine.

31. The combination with mechanism for applying wrappers to individual articles to be wrapped, of an accumulating chamber, means for conveying the individually wrapped articles from the wrapping mechanism to the accumulating chamber, a second wrapping mechanism for applying wrappers around a predetermined number of individually wrapped articles, means for conveying the individually wrapped articles in predetermined quantities from the said accumulating chamber to the last said wrapping mechanism, means comprising a vertically-moving plunger for introducing a predetermined number of individually wrapped articles into the last said wrapping mechanism and folding the longitudinal side flaps of the wrappers, a reciprocating folder for folding the rear longitudinal side flap of the wrapper, a spring-pressed plate at the rear side of the folding mechanism under which the package is adapted to be passed to fold the forward side flap, a reciprocating transport for conveying the package beneath the said plate and folding the forward longitudinal flap, means for crimping and folding the ends of the wrapper around the package of individually wrapped articles interposed in the path of the article beneath the said spring-pressed plate, a binder applying and pasting mechanism, means for transferring the wrapped package from the last said wrapping mechanism to the binder applying and pasting mechanism, and means for discharging the completely wrapped package with the binder applied and pasted thereon from the machine.

32. The combination in a machine having wrapping mechanism for applying wrappers to individual articles, of an accumulating chamber, means for discharging articles from the wrapping mechanism to the accu-

mulating chamber, a second wrapping mechanism, means for discharging individually wrapped articles in predetermined quantities from the accumulating chamber to the last said wrapping mechanism whereby the individually wrapped articles are formed into multiple-stick packages, means for applying wrappers around said multiple-stick packages, means for discharging the wrapped multiple-stick packages from the last said wrapping mechanism comprising a movably mounted top plate and a reciprocating transport coöperating therewith, a binder applying and pasting mechanism, means for transferring the wrapped multiple stick packages to the binder applying and pasting mechanism from adjacent the forward extremity of the reciprocating transport and the movable plate, and a movable stop adjacent the forward end of the transport and the movable plate to position the wrapped multiple stick packages for the said transferring means.

33. The combination in a machine having wrapping mechanism for applying wrappers to individual articles, of an accumulating chamber, means for discharging articles from the wrapping mechanism to the accumulating chamber, a second wrapping mechanism, means for discharging individually wrapped articles in predetermined quantities from the accumulating chamber to the last said wrapping mechanism whereby the individually wrapped articles are formed into multiple stick packages, means for applying wrappers around said multiple-stick packages, means for discharging the wrapped multiple-stick packages from the last said wrapping mechanism comprising a movably mounted top plate and a reciprocating transport coöperating therewith, a binder applying and pasting mechanism, means for transferring the wrapped multiple-stick packages to the binder applying and pasting mechanism from adjacent the forward extremity of the reciprocating transport and the movable plate, and a movable stop adjacent the forward end of the transport and the movable plate to position the wrapped multiple stick packages for the said transferring means.

34. The combination in a machine having wrapping mechanism for applying wrappers to individual articles, of an accumulating chamber, means for discharging articles from the wrapping mechanism to the accumulating chamber, a second wrapping mechanism, means for discharging individually wrapped articles in predetermined quantities from the accumulating chamber to the last said wrapping mechanism whereby the individually wrapped articles are formed into multiple stick packages, means for applying wrappers around

- 5 said multiple stick packages, means for discharging the wrapped multiple stick packages from the last said wrapping mechanism comprising a movably mounted top plate and a reciprocating transport coöperating therewith, a binder applying and pasting mechanism, means for transferring the wrapped multiple stick packages to the binder applying and pasting mechanism
- 10 from adjacent the forward extremity of the reciprocating transport and the movable plate, and an elastically controlled movable stop adjacent the forward end of the transport and the movable plate to position the
- 15 wrapped multiple stick packages for the said transferring means.
35. The combination in a machine having wrapping mechanism for applying wrappers to individual articles, of an accumulating chamber, means for discharging articles from the wrapping mechanism to the accumulating chamber, a second wrapping mechanism, means for discharging individually wrapped articles in predetermined quantities from the accumulating chamber to the last said wrapping mechanism whereby the individually wrapped articles are formed into multiple-stick packages, means for applying wrappers around said multiple
- 20 stick packages, means for discharging the wrapped multiple-stick packages from the last said wrapping mechanism comprising a movably mounted top plate and a reciprocating transport coöperating therewith, a binder applying and pasting mechanism, means for transferring the wrapped multiple-stick packages to the binder applying and pasting mechanism from adjacent the forward extremity of the reciprocating trans-
- 25 port and the movable plate, and a spring-controlled movable stop adapted to be lifted to prevent the escape of an undue accumulation of wrapped multiple stick packages.
36. The combination in a machine having
- 30 wrapping mechanism, of means for delivering wrapped packages from the wrapping mechanism comprising a reciprocating transport and a coöperating plate, mechanism for applying binders around said wrapped packages, means for transferring wrapped packages from the delivery end of the reciprocating transport and the coöperating plate to the binder applying mechanism, and a movable stop for positioning wrapped packages at the delivery end of the reciprocating transport and the coöperating plate, said movable stop being adapted to be moved out of the way by an abnormal accumulation of wrapped packages, thereby
- 35 preventing clogging of the machine.
37. The combination in a machine having wrapping mechanism, of means for delivering wrapped packages from the wrapping mechanism comprising a reciprocating
- 40 transport and a coöperating plate, mech-
- 45 anism for applying binders around said wrapped packages, means for transferring wrapped packages from the delivery end of the reciprocating transport and the coöperating plate to the binder applying mechanism, and an elastically controlled pivoted stop for positioning wrapped packages at the delivery end of the reciprocating transport and the coöperating plate, said movable stop being adapted to be moved out of the way by an abnormal accumulation of wrapped packages, thereby preventing clogging of the machine.
38. The combination in a machine having wrapping mechanism for applying wrappers to individual articles, a second wrapping mechanism for applying wrappers to a predetermined number of singly wrapped articles, means for accumulating a predetermined number of singly wrapped articles, transferring means for conveying a predetermined number of singly wrapped articles from the accumulating means to the last said wrapping mechanism, and means for rendering said transferring means inoperative upon an undue accumulation of articles to be wrapped either in the said accumulating means or in the last said wrapping mechanism.
39. The combination in a machine having wrapping mechanism for producing wrapped packages, of a binder applying and pasting mechanism, means for discharging wrapped packages from the wrapping mechanism, means for transferring wrapped packages from the wrapping mechanism to the binder applying and pasting mechanism, and means for rendering said transferring means inoperative upon an undue accumulation of wrapped packages either at the discharge end of the wrapping mechanism or in the binder applying and pasting mechanism.
40. The combination in a machine having wrapping mechanism for producing wrapped packages, of means for discharging wrapped packages therefrom comprising a reciprocating transport, binder applying mechanism, a rotatable shaft, an arm carried on said shaft and being provided with elastically controlled separable jaws adapted to engage wrapped packages adjacent the wrapping mechanism and to move in the arc of a circle on said rotatable shaft to deliver the wrapped packages to the binder applying mechanism, and means carried by the said reciprocating transport for operating the said separable jaws to cause them to engage the wrapped packages at the delivery end of the transport.
41. The combination in a machine having wrapping mechanism, of binder applying mechanism, means for transferring wrapped packages from the wrapping mechanism to the binder applying mechanism comprising

- an arm carrying suitable elastically controlled gripper-jaws adapted to engage the packages and convey the same through the arc of a circle to the binder applying mechanism, a rocking shaft on which said arm is carried, and a spring controlled plunger on the said arm engaging a depression on the rocking shaft whereby the arm is adapted to be actuated positively by said shaft during the normal operation of the arm in transferring wrapped packages from the wrapping mechanism to the binder applying mechanism but will permit the arm to remain inoperative should the machine become obstructed with wrapped packages either at the delivery end of the wrapping mechanism or at the binder applying mechanism.
42. The combination with wrapping mechanism, of a stick accumulating mechanism, a binder applying mechanism, a pivoted arm provided with gripping means for transferring wrapped articles from the stick accumulating mechanism to the binder applying mechanism, and means for actuating said arm.
43. The combination in a machine having wrapping mechanism, of a magazine for containing articles to be wrapped, means for delivering articles from the magazine to the wrapping mechanism, said means being adapted at each operation thereof to remove articles to be wrapped in predetermined quantities and comprising a slotted reciprocating member, means for operating the said slotted reciprocating member from the wrapping mechanism to the path of the articles within the magazine, and means for longitudinally positioning the articles in the carrying slots of the reciprocating member to insure correct delivery of the articles to the wrapping mechanism.
44. In a binder applying mechanism, the combination of a binder feeding roll, a pair of supplemental binder feeding rolls receiving and feeding the binder from the first said roll, a guide adjacent the said rolls for directing the binder across the path of the material to be banded, a member at the other side of the path of the material for supporting one end of the binder, paste rolls adjacent said member being adapted to engage the binder while being moved by the said supplemental rolls, and a stop on the member for the ends of the binder.
45. In a binder applying mechanism, the combination with a binder feeding roll adapted to under-lie a vertical stack of cut binders and in normal contact with the lower-most binder in the stack, of a guide for directing the binder across the path of the material to be banded, a supplemental binder feeding device interposed between the said binder feeding roll and the said guide, comprising two contiguous co-oper-

ating rollers, an adjustable stop interposed in the path of the binders as they are fed through said guide, said adjustable stop being provided with a projecting lip adapted to support the lower forward edge of the binder, and a positively driven paste applying roll being adapted to feed the forward edge of the binder over the said lip to the stop on said guide.

46. In a binder applying mechanism, the combination with a reservoir for containing a plurality of cut binders in a vertical pile or stack, a feeding roll under-lying the said stack of cut binders and being adapted to contact with the lower-most binder therein for feeding the same from the stack, a guide for directing the binder, a pair of cooperating supplemental feeding rolls interposed between the guide and the said feeding roll, an adjustable plate interposed in the path of the binders as they are fed from the said guide by the feeding roll and the said supplemental feeding rolls, said adjustable plate being provided with a stop for limiting the movement of the forward edge of binders fed through said guide, there being a lip or projection on said plate adapted to underlie the said stop portion thereon, for the purpose of supporting the forward edge of the binders as they are fed from said guide, and a positively driven paste applying roll adjacent the lip on said adjustable plate and being adapted to feed the forward edge of the binder into contact with the stop portion of the plate, and to apply paste thereto.

47. In a machine for wrapping, grouping and banding flat, thin articles, mechanism for folding the wrappers about said articles, mechanism for assembling the wrapped articles, in groups and for applying confining bands to said groups, said last mentioned mechanism comprising paste applying means, binder feeding means, a folding member, there being a space between said binder feeding means and said folding member, means for carrying the material to be banded through the said space to fold the flaps of the binder to a vertical position, means for compressing the rear vertical side flap of the binder against the package, means for folding the rear vertical flap of the binder, and means for discharging the package beneath the folding member to fold the last binder flap upon the package.

48. In a machine for wrapping, grouping and banding flat thin articles, mechanism for folding the wrappers about said articles, mechanism for assembling the wrapped articles in groups and for applying confining bands to said groups, said last mentioned mechanism comprising paste applying means, binder feeding means, a folding member, there being a space between said binder feeding means and said folding

member, means for carrying the material to be banded through the said space to fold the flaps of the binder to a vertical position, reciprocating means for compressing the 5 rear vertical side flap of the binder against the package, means for folding the rear vertical flap of the binder, and means for discharging the package beneath the folding member to fold the last binder flap upon the 10 package.

49. The combination in binder applying mechanism, of a receptacle for cut binders, means for feeding said binders, paste applying means, means for feeding the articles 15 to be banded, means for folding the flaps of the binder to the vertical position, means for compressing one side of the partially banded package for taking the slack out of the rear side flap, means for folding the rear 20 side flap flat on the binder, means for positively discharging the package, and means for folding the final flap of the binder flat upon the top of the package during the discharge movement of the package.

50. The combination in binder applying mechanism, of means for feeding a plurality of articles to be banded, means for supplying a cut binder, paste applying mechanism, means for folding the side flaps 30 of the binder to a position at approximately right angles to the bottom of the package, means for compressing one of the side flaps upon a longitudinal side of the package, means for folding the compressed flap flat 35 upon the package, means for folding the last side flap flat upon the package and the previously folded flap of the binder, and means for positively discharging the package.

51. In a binder applying mechanism, the combination of binder feeding means, means for carrying the articles to be banded to the binder applying mechanism, means for folding the ends of the binder to a vertical position 45 around the longitudinal sides of the package and at approximately right angles to the bottom of the package, means for compressing one of the vertical flaps of the binder on a longitudinal side of the package, means for folding said compressed 50 binder flap flat upon the package, means for folding the last side flap of the binder flat upon the package and upon the previously folded flap of the binder, and means for 55 positively discharging the package from the binder applying mechanism.

52. In a binder applying mechanism, the combination of means for feeding the material to be banded, means for supplying 60 binders, means for folding the binder around three sides of the material to be banded with approximately parallel projecting side flaps, means for compressing one of the side flaps upon the longitudinal

side of the article to be banded prior to the 65 folding of said flap, means for folding the flap flat upon the package, means for folding the last flap of the binder flat upon the package and upon the previously folded flap, and means for discharging the package. 70

53. In a binder applying mechanism, the combination of means for supplying binders, means for feeding the articles to be banded to the binders, means for applying 75 the binders to three sides of the package with the projecting end flaps approximately parallel to each other, means for compressing one of the projecting binder flaps against the side of the package, means for subsequently folding said projecting side 80 flap flat upon the package, means for applying paste to the remaining binder flap, means for folding said remaining binder flap flat upon the package and upon the previously folded binder, flap, and means for discharging the package.

54. The combination with folding mechanism, of means for operating said mechanism comprising a cam, driving means for 90 said cam, a clutch between said driving means and said cam, means for operating said clutch, means for supplying articles to be wrapped to the folding mechanism, a movable member lying in the path of said 95 articles, a connection between said movable member and said clutch-operating means, and a member adapted to engage said cam for controlling the movements of said clutch-operating member and the movable 100 member in the path of the articles.

55. The combination with wrapping mechanism, of movable means for placing material in operative relation to said wrapping mechanism, driving means, a clutch between 105 said wrapping mechanism and said driving means, and means for operating said clutch comprising two pivoted arms, a movable member connecting the free ends of said arms, said movable member lying in the 110 path of movement of said material to be wrapped, a spring tending to operate said movable member in the direction opposite to that in which the material to be wrapped moves through the wrapping mechanism, 115 and means for operating said clutch comprising means operatively connected with said movable member.

56. In a machine for wrapping, grouping and banding articles, mechanism for folding the wrappers about the articles, mechanism for grouping the wrapped articles and applying binders to the groups and pasting them thereon, said latter mechanism comprising means for folding the binder, driving 120 means, a clutch between said folding means and said driving means, and means adapted to be engaged by the material upon 125

being inserted into the folding mechanism for operating said clutch.

- 5 57. The combination with wrapping mechanism, of a table adjacent said wrapping mechanism, means for operating the wrapping mechanism, means for discharging wrapped articles from said wrapping mechanism onto said table, means for guiding said wrapped articles from the table into 70
10 packing boxes comprising a guide member of less width than the interior width of the packing box, and end guide members on the table top leading to and converging toward the said guide member.
- 15 58. The combination in a wrapping machine, of wrapping mechanism, a vertically reciprocating member provided with picks moving toward and from said wrapping mechanism and being adapted to press the 75
20 articles to be wrapped into said wrapping mechanism, a plunger for feeding articles to be wrapped movable to and from the path of said reciprocating member and being provided with an upwardly opening 80
25 slot to contain the article to be wrapped, means for advancing the reciprocating member whereby the article is impaled on said picks, means for withdrawing the reciprocating member to lift the impaled article 85
30 above the slots in said feeding plunger, means for withdrawing said feeding plunger from the path of movement of said reciprocating member and means for advancing said reciprocating member to press the 90
35 article into the wrapping mechanism.

59. The combination in a machine having wrapping mechanism, of a magazine containing articles to be wrapped, means for delivering articles from the magazine to the 100
40 wrapping mechanism, a support for wrapping material, a reciprocating plate, a plurality of nipper jaws secured to and coöperating with the said plate to grasp the wrapping material and draw the same over 105
45 the wrapping mechanism, means for closing the nipper jaws on the wrapping material, a plunger adapted to force the article into the wrapping mechanism on top of the wrapping material, means for operating 110
50 said plunger, and means operated by said plunger operating means for opening the nipper jaws to release the wrapping material.

60. The combination in a machine having 115
55 wrapping mechanism, of a magazine for containing articles to be wrapped, means for delivering articles from the magazine to a position adjacent the wrapping mechanism, means for supporting wrapping material, means for feeding the wrapping material from the said support to the wrapping mechanism, a reciprocating plunger adjacent the wrapping mechanism, picks carried by said plunger being adapted to impale the 120
60 article to be wrapped and to force the same

into the wrapping mechanism on top of the previously positioned wrapping material, and means operated by said reciprocating plunger for releasing the means for feeding the wrapping material.

61. The combination in a machine having wrapping mechanism, of means for supporting wrapping material, means for drawing the wrapping material to the wrapping mechanism comprising a reciprocating plate, a plurality of nipper jaws pivotally connected with said plate, each of said jaws being independently movable with relation to each other, means for operating said jaws to close them simultaneously upon the wrapping material, means for reciprocating the plate to which said jaws are secured, and means for releasing the jaws simultaneously from the wrapping material. 75
80

62. The combination in a machine having wrapping mechanism, of means for delivering articles to the wrapping mechanism to be wrapped, a support for wrapping material, means for feeding the wrapping material to the wrapping mechanism comprising a movable plate, a plurality of nipper jaws pivotally connected to and coöperating with said plate, a standard supporting said plate, a link connection between the said standard and said nipper jaws for controlling the movement thereof, and adjustable means secured to said standard for controlling the movement of said links. 90
95

63. The combination in binder applying mechanism, of means for containing a quantity of cut binders, a binder wrapping box, a roller for applying mucilage to binders in position over the wrapping box, a guide plate upon which the binders are held while being acted upon by the mucilage applying roller and a stop on said guide plate adapted to coöperate with said plate and roller to position the binder in relation to the binder wrapping box, and prevent displacement of the binder by contact with the roll. 100
105

64. The combination in a wrapping machine, of means for supporting wrapping material, wrapping mechanism, and mucilage applying mechanism comprising a roller and a coöperating plate, said mucilage applying means being situated on the side of the binder wrapping mechanism opposite the binder feeding means, and a stop on the said coöperating plate for positioning the binders over the wrapping mechanism, and prevent displacement of the binder by contact with the roll. 110
115

65. In a wrapping machine, the combination with a wrapping box, of means for supporting wrappers, means for feeding the 120
125 wrappers to the wrapping box, means for transferring articles to be wrapped to the wrapping box, mucilage applying means on the side of the wrapping box opposite the wrapper feeding mechanism, and a stop on 130

the said plate coöperating with the mucilage applying roll to position the wrapper in relation to the wrapping box, and prevent displacement of the binder by contact with the roll.

66. The combination in a machine having wrapping mechanism, of a magazine for containing articles to be wrapped and means for delivering articles from the magazine to the wrapping mechanism, said means comprising a reciprocating feed member adapted to take articles singly from the bottom of the magazine, said feed member being provided with means for applying a reciprocatory movement thereto and an additional or secondary reciprocatory movement at the instant that it engages articles in the magazine.

67. The combination in a machine having wrapping mechanism, of a magazine for containing a vertical column of articles to be wrapped, means for discharging articles from the magazine, said means comprising a slotted, movably-mounted member adapted to engage articles at the bottom of the vertical column within the magazine, means for reciprocating said slotted member to discharge articles from the vertical column, and means for imparting an additional secondary or short vibratory movement to said member to cause the vertical column to settle to the bottom of the slot therein.

68. The combination in a machine having wrapping mechanism, of a magazine for containing a vertical column of articles to be wrapped, means for discharging articles from the magazine comprising a slotted, movably-mounted member adapted to engage articles at the bottom of the vertical column within the magazine, and means for

operating said slotted, movably-mounted member comprising a rotary cam provided with an eccentric cam track and suitable connections between said cam and said slotted member, there being a short irregular break in said cam track whereby an additional secondary or short vibratory movement is imparted to said slotted member to cause the vertical column to settle to the bottom of the slot therein.

69. The combination with a magazine for containing articles to be wrapped, of wrapping mechanism, means for discharging articles from the magazine and conveying and presenting the same to the wrapping mechanism, means for holding a supply of wrapping material in strip form, means for drawing the free end of a strip of wrapping material over the wrapping mechanism, means for severing a wrapper from said strip, and an elastically controlled member interposed between the means for containing the supply thereof and the folding-box and being adapted to normally deflect a portion of the strip, whereby slack material may be maintained in the strip to be utilized when desired in forming a wrapper, making it unnecessary for the material used in forming a wrapper to be completely drawn from the supply at each operation of the wrapper drawing means.

In testimony whereof we have signed our names to this specification, in the presence of two subscribing witnesses, on this 23rd day of December, A. D. 1910.

FRANK B. REDINGTON.
MICHAEL J. MILMOE.
